UNITED STATES PATENT OFFICE.

HUBERT S. TURNER, OF SAN DIEGO, CALIFORNIA.

TELEPHONY.

1,402,691.

Specification of Letters Patent. Patented Jan. 3, 1922.

Application filed May 20, 1916. Serial No. 98,822.

To all whom it may concern:

Be it known that I, HUBERT S. TURNER, a citizen of the United States, residing at San Diego, in the county of San Diego and

5 State of California, have invented certain new and useful Improvements in Telephony.

The present invention has for its principal object the provision of means whereby all the incoming calls to a telephone exchange switchboard are automatically distributed evenly amongst whatever idle operators may happen to be on duty at one time, means being provided to prevent an operator from receiving two or more simultaneous calls, and to prevent a call from

10 being received while a call previously received has not been completed through. Means are also provided, operative when a sub-station is connected to a link connector

20 or cord circuit, whereby the operation of a "disconnect" or "recall" signal associated with the link connector makes the connecting operator nonselectable by an incoming call as long as said signal is in operation. Means

25 are also provided, operative only when all the operators on duty are engaged in completing calls, to operate a signal should there be a calling line waiting to be answered by an operator, the repeated operation of this

30 signal indicating that another operator or other operators are needed at the switchboard. Means are also provided to indicate when the incoming calls are coming in below the working capacity of the operators

35 who may be on duty at any time, thereby allowing one or more of the operators to be removed. Other objects will be apparent from the specification.

Call distributing systems have many well known advantages, amongst which are found the following:—

40 Fewer operators needed.

Elimination of the intermediate frame.

Quicker operator's response to the calling lines.

45 Saving of lamp and answering jack space at switchboard.

Ability of a few operators to handle the off peak load.

50 Call distributing systems have heretofore been open to many objections, amongst which are found the following, all of which are eliminated in the system of my invention:—

Complexity and expense of apparatus.

Time lost while selector switch mechanism 55 is selecting an idle operator.

Two or more calls simultaneously put through to the one operator.

A greater number of calls put through to the first operators selectable than to the other 60 operators, whereby some operators are kept working at capacity whilst others remain more or less idle.

Only a portion of the available operators at a switchboard selectable by a given line 65 or, if all the operators are available thereto, a lack of means whereby simultaneous calls are simultaneously put through to different operators.

In the system of my invention no selector 70 switch or other complicated electrically operated mechanism is used, instead, the calls are properly distributed by means of simple relays of well known forms. The entire number of relays used in an exchange served 75 by this system of call distribution, as described herein, is from 70 to 128 per cent of the number used in most of the well known exchange systems where the lines terminate in a cut-off and line relay and the cord circuits comprise two supervisory relays.

The number of relays used varies according to which of the described forms of distributing equipment and cord circuit is used and the number of operators to which each 85 subscriber has access. Therefore, as well as obtaining all the advantages inherent in my improved form of call distributing system, I can effect an economy in apparatus and exchange space at the same time. The 90 above mentioned percentages of equipment are based on a 10,000 line exchange; 1,000 cord circuits and from 30 to 60 operators.

In this system no attempt is made to automatically connect a calling line direct to a 95 link connector or connecting cord at a switchboard position where the operator is idle. Instead, means are provided for automatically indicating to an idle operator the number of the calling line, whereupon the 100 operator inserts an answering plug in a multiple jack of the line, obtains the number of the desired line and completes the call by inserting the calling plug in a jack of the called-for line. A feature of the invention 105 is that an operator is non-selectable by a calling line only when an answering plug is connected to a line which is actually calling

and the corresponding calling plug has not been inserted in a jack or when receiving the aforementioned disconnect or recall signals, whereby an operator has no personal control over the means which renders a position non-selectable by a calling line.

In the following description reference will be had to my U. S. Patent No. 1,128,262, and my co-pending applications Serial Nos. 10 45,232 and 64,967, as the present application, in regard to the link connector circuits, in some respects consists in modified means for accomplishing the results described therein.

In order to more fully describe my invention, reference will be had to the accompanying drawings forming a part of this specification, and wherein:—

In Figure 1, Part 1 is a diagram illustrating all the exchange apparatus individual to one hundred lines, when each line has access to nine operators (one additional relay being added to the equipment shown for each additional three operators) and the signal means used which is common to the entire exchange; Part 2, a diagram illustrating in part the apparatus individual to the operators' positions at the switchboard and a part of the apparatus individual to other lines; Part 3, a diagram illustrating various types 30 of link connectors or cord circuits which are adapted for use with the described call distributing system; Figure 2, a diagram illustrating a modification of a part of Figure 1; Figure 3, a diagram illustrating the use of the described call distributing system combined with a system where some of the lines terminate in answering jacks at a particular operator's position at the switchboard; Figure 4, a diagram illustrating various modifications of the apparatus illustrated in Figure 1; Figure 5, a diagram illustrating a modification of a part of Figure 4, and Figure 6, a diagram illustrating a modification of a part of Figure 1, Part 2.

The lower end of Sheet 2 of the drawings is intended to join the upper end of Sheet 1, the wires ending thereat being continuous and connecting Part 1 to Part 2. The wires terminating at the upper ends of Sheets 2 and 3 are continuous and connect Part 2 to Part 3.

For sake of convenience, the talking circuits and principal traced circuits are shown by means of heavy lines. Also the relay and terminal reference numerals inserted in parentheses represent the actual signal numbers controlled by the instrumentality designated thereby.

Referring first to Parts 1 and 2: In the 60 preferred embodiment of my invention I eliminate the line relays which are usually individual to the substation lines, and instead use twenty line relays common to each unit of one hundred lines. Ten of these 65 relays represent the units (0) to (9) and ten

represent the tens (00) to (90). As the units and tens relays are operated directly through the substation lines, it is advisable to make these relays of a single pole sensitive type; therefore, the tens relays close a local circuit 70 through the multi-pole relays 0 to 9 respectively, in order to perform the necessary switching operations. It will readily be understood that, where conditions permit it, the tens relays could perform the switching 75 operations controlled by relays 0 to 9.

For purpose of illustration, the exchange described hereinafter may be considered as consisting of ten thousand lines, numbered respectively from 0000 to 9999, it being 80 readily understood that the disclosed system is not limited to any specific number of lines, the amount of apparatus used varying proportionately with the number of lines served.

I have shown at 10 a telephone substation 85 of a well known form, to the use of which form the invention, however, is not to be limited. As illustrated, this substation would correspond to number 0001. The removal of the telephone receiver at this substation gives 90 path for current from battery 11 through elements 12, 13, 14, 15, 16, 17, 18, 19, 20, line relay (00), 21, 22, 23, 24, 25, 26, 27, 28, 29, 30, 31, 32, 33, line relay (1) and ground, energizing relays (00) and (1). This gives 95 path for current from battery 11, through elements 12, right winding of section selecting relays 34, 0, 35, 36 and ground, energizing relays 34, and 0. As soon as contact 37 of battery control relay 0 after first engaging 100 contact 20, disengages the latter from contact 19, the traced circuit through contact 19 is opened and the path for the current from interrupter 14 now proceeds by way of line 38, winding of battery cut-off relay 39 and 105 contact 37 of relay 0, energizing relay 39.

As the current passing through primary 25 of substation 10 is a variable one (due to the same passing through interrupter 14), though the same is not intermittent (due to 110 the resistance which shunts the interrupter), an audible signal is produced in the receiver at substation 10 which continues until the operator answers the call.

The energization of relays 0 and 34 also 115 gives path for current from battery 40 (Part 2) through elements 41, 42, 100, 43, 44, 45, 46, 47, upper winding of section connecting relay 48, 49, 50, 51, 52, 53, 54, 55, 56, 57, 58 and 59 to the other pole of battery 40, energizing relay 48. This gives a shunt path, to that part of the traced circuit between elements 45 and 52, through the left winding of relay 34, lower winding of relay 48, elements 61, 62, 63, thousand signal relay (0000), 64, 120 65, 66 and call transfer relay 67.

The upper winding of relay 48 is preferably of a higher resistance than the lower winding, as shown, though it is not essential, as it is only necessary that enough current 125 130

passes through the left winding of the differentially wound relay 34 to neutralize the magnetic effect produced by the current flowing in the described circuit through the right 5 winding, thereby de-energizing the relay. When contact 46 becomes disengaged from contact 47, the described circuit through the upper winding of relay 48 is opened and all the current now flows through the lower 10 winding of relay 48, maintaining the same actuated. Relays (0000) and 67 (Part 2) are preferably, though not necessarily, energized only after the opening of the circuit through the upper winding of relay 48, when 15 they receive all the current flowing in the circuit. This is purely a precautionary measure, it only being necessary that contact 46 of relay 34 disengage contact 47, before contact 51 of relay 67 engages contact 20 68. If the two relays were energized simultaneously, the adjustment of contacts 51-68 would be such that they could not engage before contacts 46-47 had become disengaged.

25 The energization of relay 48 (Part 1) gives another path for current from battery 40 through elements 41, 69, 70, 71, 72, 73, 74, 75, 76, hundred signal relay (000), 77, 78, 57, 58 and 59 to the other pole of battery 30 40, energizing relay (000).

The energization of relay 67 (Part 2) also gives path for current from battery 11 through elements 79, 80, 81, 82, 83 and 84; or 85, 86 and 87; or 88, 89 and 90; and 91, 92, 35 93, energizing signal controlling relay 84, 87 or 90 according to the position of interrupter 81 in relation to its brushes.

As well as the relay circuits closed, as described, whenever a substation receiver is 40 taken off its switchhook, signal talking circuits are also closed through an operator's receiver such as 94 (Part 2) which corresponds to the operator selected by section connecting relay 48. These signal talking 45 circuits are adapted to transmit by phonographic means the line designation of the calling line, thereby allowing the operator to pick out the correct line jack in the multiple and connect the talking set thereto by 50 way of an answering cord and plug, the operation of connecting the talking set opening the aforementioned signal circuits, de-energizing all the described relays, and eliminating the audible signal in the receiver 55 at substation 10.

The phonographic signal means is shown in Part 1, wherein 95 represents a phonographic record, which may be of the cylindrical form as shown, or of the disk or other 60 type. This cylinder or disk has recorded on its surface the repeated record of all the spoken numbers from 0 to 9, or the record of any other form of line designations. The members are so recorded that they are repeated four times with a short interval be-

tween each repetition, then a longer interval and the numbers repeated again with the short interval between them. Cylinder 95 is rotated by means of motor 96 which is geared thereto, or by any other rotating 70 means. Interrupter 81 is revolved in synchronism with cylinder 95, it being geared to the cylinder as shown or to motor 96. The number of repetitions on each cylinder or disc will depend upon its size, as, preferably, 75 the record of the recording voice used does not trace the usual spiral upon the record, but makes one complete circle around the same. Bearing upon the record and adjusted in the groove representing the voice vibrations of the number 0, is the needle or stylus of a phonographic reproducer 97, which is associated with a telephone transmitter 98 so as to produce therein the necessary vibrations of its diaphragm and to cause the transmitter to transmit the correct electrical fluctuations to the circuit controlled by it, and thereby reproduce by well known telephonic means the corresponding number in a telephone receiver which may be associated with 80 said transmitter circuit. The circuit for transmitter 98 may be traced from battery 11 through wire 79, transmitter 98 and primary 99 to ground. Therefore, any receiver connected to secondary 42 will have repeated 85 into it the number 0. For sake of clearness I have not shown in the drawing the usual retardation coil placed in series with the transmitter when the same is connected to the exchange battery, as illustrated, nor the 90 condenser which usually shunts the primary and transmitter, the use of the same being well known in the art.

The described energization of thousand signal relay (0000) connected operator's receiver 94 to secondary 42 by way of a circuit which may be traced as follows: From the right terminal of the secondary through elements 100, 101, 102, 103, 104, 105, 106, 107, 108, 109, 110, 111, 112, 113, 114, 115, 110 116, 94, 117, 118, 119, 120, 55, 56, 57, 58, 59, 40 and 41 to the left terminal of the secondary. Therefore, the number 0 corresponding to the 0 thousands in the exchange is sounded in receiver 94. Interrupter 81 115 revolves so that its metallic segment engages brush 82 before the next repetition of the numbers on record 95 takes place, consequently, relay 84 is energized and contact 107 disengages contact 106 and engages 120 contact 121. Therefore, secondary 42 is disconnected from receiver 94 by way of the traced circuit and is connected thereto again by way of a circuit which may be traced as follows: From the right terminal of secondary 42, through elements 100, 101, 122, 123, 124, 125, 126, 121, 107 and by the traced path through receiver 94, battery 40 and wire 41 to the left terminal of secondary 42. As secondary 42 is associated with the 130

same primary that is in circuit with transmitter 98, which transmits the number 0 as reproduced by the phonographic record, that number, corresponding to the 0 hundreds 5 in the exchange is sounded in receiver 94. During the short silent interval between the repetition of the numbers as reproduced by the phonograph, the metallic segment of interrupter 81 disengages brush 82 and engages brush 85, thereby de-energizing relay 84 and energizing relay 87. Contact 109 thereupon disengages contact 108 and engages contact 127, thereby furnishing a shunt path through receiver 94 for the voice 10 currents from secondary 42 which have heretofore been passing through the described circuit through contacts 43-44 of relay 0, relay 0000, wires 64-65, retardation coil 66 and wire 57 to battery 40. On account of 15 the impedance of retardation coil 66, sufficient voice currents from secondary 42 are shunted through receiver 94; therefore the number 0, corresponding to the 0 tens is sounded in receiver 94. If preferred, relay 20 67 can be made of the necessary impedance, thereby eliminating retardation coil 66. During the next short silent interval between the repetition of the numbers as reproduced by the phonographic record, the 25 metallic segment of interrupter 81 disengages brush 85 and engages brush 88, thereby de-energizing relay 87 and energizing relay 90. Contact 111 thereupon disengages contact 110 and engages contact 128, thereby 30 furnishing a shunt path through receiver 94 for the voice currents from secondary 69 which have heretofore been passing through the described circuit through contacts 70-71 of relay (1), relay (000), retardation coil 40 77 and wire 78 to battery 40. On account of the impedance of retardation coil 77 sufficient voice currents from secondary 69 are shunted through receiver 94; therefore, the number 1, corresponding to the 1 units is 45 sounded in receiver 94, inasmuch as secondary 69 is associated with the primary which is in series with transmitter 129 which in turn reproduces the number 1, as hereinbefore described. In this way the number 50 "0001" is sounded in operator's receiver 94. After sounding the units number, the metallic segment of interrupter 81 disengages brush 88 and, consequently, relay 90 is de-energized. As the de-energization of this 55 relay is synchronous with the long silent interval between the repetition of the phonographic numbers, the long interval forms a space between the sounding of a number and its repetition, thereby indicating to the operator the last or unit number. Just before the metallic segment of interrupter 81 engages brush 82 again the first of the series of phonographic repetitions of the numbers takes place, consequently, the number 60 0 is reproduced again and the numbers 65

0-0-1 follow in quick succession. Brushes 82, 85, 88 of interrupter 81 are individual to the first switchboard section, there being corresponding brushes for each of the other sections, thereby preventing shunt paths 70 through the other signal controlling relays corresponding to 84, 87, 90, when contacts 92-93 of relay 67 become engaged. Instead of individual brushes the upper terminals of relay 84, 87, 90 may lead to separate 75 contacts such as 92, being connected together and grounded only when relay 67 is energized, as shown in Figure 2.

The lower winding of relay 48, left winding of relay 34 and relays (000)-(0000) 80 may be bridged by condensers, as shown, or non-inductive resistances may be substituted therefor, in order to allow the voice currents from the described secondaries a freer path to receiver 94. However, the inductive windings of these relays may be such, or the voice currents produced by the described secondaries may be so strong, or both, that the use of such condensers or non-inductive resistances is not necessary. 90

From the description of the means for repeating the number of the calling line, it will be evident that if the operator does not understand the number when it is first sounded, it will only be necessary to wait 95 for it to be repeated. If the signal connection is established by the calling line at the time the metallic segment of interrupter 81 is engaged with brush 82, is between that brush and brush 88, or is engaged with the latter, thereby sounding an incomplete number, the sounding of one, two or three numbers only would indicate to the operator that the number was incomplete and the operator would wait for the next repetition which 100 would necessarily be the complete number. The time interval between the repetition of the complete numbers can be made very short so that an appreciable amount of time 105 is not lost by having the operator wait. 110

Referring now to Part 3. I have shown therein five different forms of link connectors which may be used with the described call distribution system. However, it will be seen as these link connectors are described 115 that any standard link connector circuit may also be used.

By placing the sheet containing Part 3 at the right of the sheet containing Part 2, the four lines shown at the top of each sheet will be found to correspond and are intended to be connected. 120

The link connector marked A represents a well known type and I have made no change therein. If the exchange is equipped with 125 this type of link connectors then when the operator inserts answering plug 132 in a multiple jack 133 or 134 (Part 1) of the calling line, path is given for current from battery 135 through elements 136, 137, 138, 130

139, 140, 141, or 142 (Part 1) 143 and to ground, energizing cut-off relay 143 and supervisory lamp 139. Contacts 23—31 of relay 143 disengage contacts 22—32, thereby 5 opening the traced circuit through relays (00) and (1) and de-energizing the same. Consequently, the circuit through relay 0 and the right winding of relay 34 is opened when contacts 35—36 of relay (00) are dis- 10 engaged. The disengagement of contacts 43—44 of relay 0 opens the traced circuit through the left winding of relay 34, lower winding of relay 48 and relays (0000) and 67, consequently, these relays are de-energized. 15 The disengagement of contacts 74—75 of relay 48 or 70—71 of relay (1) opens the traced circuit through relay (000), thereby de-energizing the latter. The disengagement of contacts 37—20 of relay 0 opens the 20 traced circuit through relay 39, thereby de-energizing the latter. The disengagement of contacts 92—93 of relay 67 opens the traced intermittent circuits through relays 84, 87 and 90, consequently, the latter cease 25 to be intermittently energized. The sounding of the described numerical signals ceased when the relays were returned to their normal de-energized condition, as described, and the same relays are thereby made available 30 for use by other calling lines, as will be described hereinafter.

Before or after inserting answering plug 132 in a jack of the calling line, the operator manipulates listening key 144, giving path 35 for current from battery 135 through elements 136, 145, 146 and 147 in multiple, upper spring of key 144, 148, 149, upper or secondary winding of induction coil 150, 94, 117, 151, 152, 153, 154, lower spring of key 40 144, 155 and to ground, energizing position 155 and to ground, energizing position controlling relay 152. This gives path for current from battery 156 (Part 2) through elements 157, upper winding of position lock-out relay 158, 159, 160, 161, 162, upper 45 winding of position signal transfer relay 163, middle winding of induction coil 150 and to ground, energizing relays 158—163. (The middle winding of induction coil 150 is not necessary when link connector A is 50 used but is necessary when link connectors B, C, D or E are used.) The disengagement of contacts 115—116 of relay 163 and contacts 119—120 of relay 158, disconnects operator's receiver 94 from the numerical signal 55 circuit traced through said contacts and receiver, thereby preventing another calling line from sounding its number in said receiver.

Operator's transmitter 164 is included in 60 a circuit comprising jack 165, relay 166, lower or primary winding of induction coil 150 and battery 167. Therefore, the operator is enabled to converse with the calling party at substation 0001, inasmuch as the 65 traced circuit through relay 152 connected

secondary of induction coil 150 and receiver 94 to windings 145—155 of the link connector repeating coil; substation 0001 being connected to windings 168—169 of the same coil by way of contacts 170—171 of plug 132 70 and the spring contacts of jack 141 or 142. Voice currents are allowed to pass relay 152 by bridging the same with a condenser 172. Having obtained the number of the desired line the operator inserts calling plug 173 75 into a jack of the line and manipulates ringing key 174. The other functions of link connector A are not described herein as the same are well known in the art and form no part of the present invention. 80

When the operator restores listening key 144 to its normal position, the traced circuit through relay 152 is opened, consequently contacts 160—161 are disengaged and the traced circuit through the upper windings of 85 relays 158—163 is opened. However, relays 158—163 are not de-energized thereby, inasmuch as a path for current from battery 40 was given through their lower or locking windings when relay 158 was energized. This 90 path may be traced from battery 40 through elements 59, 58, 57, 56, 55, 120, 175, lower windings of relays 158—163, 176, 177, 178 and 179 to the other terminal of battery 40. Therefore, receiver 94 cannot again be connected to a calling line signal circuit until 95 either switch 176 has been opened or contacts 178—179 of lock-out release relay 180 have been disengaged. It is these locking windings and contact 175 on relay 158 and contact 178 on relay 180 which provide the means for evenly distributing the calls in an exchange amongst whatever operators may be on duty at one time. If it is desired to have an operator selectable as soon as disengaged from a calling line, switch 176 may be 100 opened, thereby preventing the use of the locking windings and making the operator selectable as soon as disengaged.

In Part 2 relays 166—163—158 and associate equipment correspond to the first operator's position at a three position section of a switchboard, relays 181—182—183 are the corresponding relays of the second position in the same section and relays 184—185—186 110 are the corresponding relays of the third position in the section. If the section comprised two positions relays 181—182—183 and associate equipment would be eliminated, and if the section comprised four positions 115 additional relays such as 181—182—183 and associate equipment would be similarly connected. It will readily be understood that any number of positions may be similarly linked together or that each switchboard section 120 may comprise but one position.

Whenever an operator vacates a position, the operator's transmitter plug is removed from its jack, thereby opening the circuit through signal switching relay 166, 181 or 130

- 8
- 184, as the case may be, and, consequently, de-energizing the same and switching the calling line signal circuit to the next position. This condition is shown at the central position of the first section. Therefore, should another call be received during the time relays 158—163 remain locked up, the path for the signal circuit which was traced through contacts 115 of relay 163 and 55 of relay 166 now proceeds by way of elements 115, 189, 190, 187, 191, 192, 193, 194, 195, 196, 197, 198, 199, 200, 201, 202, 188, 203, 204, 54 and 55, thereby producing the calling signal in operator's receiver 195 of the last position 10 in the section instead of in receiver 94 of the first position. If the operator at the central position had been on duty, then signal switching relay 181 would have been energized and contacts 187—188 would have been 15 engaged with contacts 205—206 and the signal circuit would have proceeded by way of elements 187, 205, 207, 208, 209, 210, 211, 206 and 188, thereby sounding the signal in receiver 209, and in receiver 195 only when relay 182 was locked up or energized (when the operator at the central position answered a call), thereby disengaging contact 207 from contact 208, engaging it with contact 212, and disengaging contacts 213—214. 20 When relay 163 is locked up as described, the traced circuit, closed by the calling line through the upper or operating winding of relay 48 (Part 1), which proceeded by way of contacts 50—51 of relay 67 (Part 2), 25 now proceeds by way of the middle winding of relay 163, middle winding of relay 182, and elements 215, 216, 198, 199, 200, 201, 202, 188, 203, 204, 54 and 55—56 of relay 166. The 30 middle windings of relays 163—182 are such that the current flowing in this circuit is sufficient to maintain the relays actuated, should the circuit through their lower or locking windings be opened. Therefore, should a 35 calling signal once begin to be sounded in receiver 195 of the last position, it cannot be cut off and sounded in another receiver by the operator at the central position coming on duty and energizing relay 181 by inserting the transmitter plug in jack 217, or by relay 163 of the first position being de-energized by opening switch 176, or by the disengagement of contacts 178—179 of relay 180. 40 When the operator at the second position is 45 on duty, then the path for the current through the middle winding of relay 163 would proceed by way of contacts 214—213 of relay 182 and 206—188 of relay 181, consequently, relay 163 only, would remain 50 locked up until the call was attended to and the signal circuit through receiver 209 at the second position would not be opened by the described opening of the circuit through the lower locking winding of relay 163. 55 Relays 182—183 and 185—186 are energized and locked up in the same way as described in relation to relays 163—158, consequently, when relay 185 is energized or locked up, when the operator at the last position has connected to a calling line, the circuit through contacts 215—216 of relay 185 is opened; and if relay 163 remains locked up, and either relay 182 remains locked up or relay 181 remains de-energized, the path for current through relay 48 (Part 1), 70 which was traced through wire 52 from relay 67 (Part 2), is open. Therefore, relay 48 (or any relay of another 100 corresponding thereto), which corresponds to the first switchboard section represented by receivers 94—209—195, cannot be energized by another calling line, until one of the relays 163 or 185; or 163, 182 or 185; is de-energized. 75 From the foregoing description it will be seen that more than one of the three operators at a section cannot receive a call at the same time. This arrangement is purely arbitrary and is used for purposes of economy in equipment, one operator selecting relay 80 for each 100 lines giving access to one of the three operators. As the second operator in a section is selectable as soon as the first operator has inserted an answering plug in a jack of a calling line, and the third operator similarly selectable when the second operator inserts a plug, three calls can be received in a section over the same equipment, the time needed by the first operator 85 for completing the connection for the first calling party to the called-for line, being utilized for making the other two operators selectable by way of the same equipment, inasmuch as this equipment would otherwise be idle until the first operator had completed the call. 90 100 105 110 115 120 125 130
- Whenever relay 48 is rendered inoperative, as described, a calling line in the 0000's is enabled to connect the proper numerical signal circuit to an operator's receiver at the second switchboard section, the traced path through contact 46 of relay 34 (Part 1), instead of proceeding by way of contact 47 through the upper winding of section connecting relay 48, now proceeds by way of contact 60 through the upper winding of section connecting relay 218, corresponding to the second switchboard section, elements 219, 220, 221, 222, 223, 224, 225, 226, (signal switching relay 227 corresponds to relay 166 of the first position in the first section and is therefore energized when an operator is on duty at the first position in the second section) 228, 229, 216 and then proceeding by the already traced path to battery 40, energizing relay 218. This gives a shunt path through the left winding of section selecting relay 34 and the lower winding of relay 218, (similar to that traced through the lower winding of relay 48) elements 230, 130

231, 232, 233, 234, 235, 236, 237, 238, 58, 59 and 5 battery 40. Call transfer relay 234 is energized by the current flowing in this path in the same way that the corresponding relay 67 of the first section was energized.

The described circuits and line signaling apparatus by which the numerical signals are produced in the operators' receivers, for sake of brevity and clearness in the drawing are not shown and described in relation to the second section, inasmuch as they are similar to those described in relation to the first section. Dotted line 233 represents the elements corresponding to thousand signal 10 relay (0000), wires 64-65 and retardation coil 66. Contact 239 of relay 218 is connected through elements at the second section in the same way as contact 75 of relay 48 is connected at the first section. It will 15 be understood that any contact or winding not shown connected, is connected and functions in the same way as the corresponding element of the first section. The top contacts of relays 227, 240, 241, 242 and 243; 20 the upper windings of relays 240, 244, 242, 245, 243 and 246; and the windings of relays 227, 241 and 247; as well as the operators' receivers, transmitters and induction coils are also not shown, it being understood 25 that they are connected in the same way as corresponding elements shown in the first section.

As the traced circuit through wire 63 and 30 relays (0000) and 67 controlled the production of the numerical signal in receiver 94 of the first position of the first section, in a similar way the traced circuit through the corresponding elements 232, 233 and relay 234 controls the production of the signal in 40 the receiver at the first position of the second section.

When the operator at the first position of the second section answers a call, relays 240-244 are locked up, as described in relation to the corresponding relays 163-158, 45 and relays 218-234 are de-energized as described in relation to the corresponding relays 48-67 of the first section, thereby making the same available for use by other calling lines.

The next calling line will produce the corresponding numerical signal in the receiver at the second position of the second section, inasmuch as the receiver thereat is 50 connected to the signal circuit in the same way as described in relation to the second position of the first section. The traced path through wire 222, instead of proceeding by way of contacts 223-224 of relay 240, now proceeds by way of contacts 248-249, 250-251 of relays 242-241 and contacts 252-224 of relay 240. The traced path through relay 234 to battery 40 was opened when contacts 235-236 of relay 240 55 were disengaged, but a path is still given

through relay 234 to battery 40, through the middle winding of relay 240, and elements 253, 254, 255, 256, 58 and 59.

The purpose of the middle windings of relays 240-242 is the same as that described in relation to the middle windings of relays 163-182, though they are energized in a slightly different way, the same being an alternative form which may or may not be used, as desired. The middle winding of relay 163 cannot be energized until its contacts 54-204 are engaged, thereby preventing a premature energization of the relay. Contact 236 of relay 240, which corresponds to contact 54 of relay 163, does not engage any contact when the relay is energized, but instead opens the direct path to battery 40 by way of contact 235, thereby removing the short-circuit around the middle winding of relay 240 and allowing current to flow through said winding and elements 253, 254, 255, 256 and 58 to battery 40. In both cases, the middle windings cannot be energized until after the relay has actuated.

Relays 242-245 are locked up in the same way as relays 240-244; consequently, the next call will produce the numerical signal in the receiver at the third position of the second section. The traced path through wire 222 instead of proceeding by way of contacts 248-249 of relay 242, now proceeds by way of contacts 259-260, 261-262 of relays 243-247 and contacts 263-249 of relay 242. The traced path through relay 234 to battery 40 by way of the middle winding of relay 240, was opened when contacts 253-254 of relay 242 were disengaged, but there is still a path to battery 40 through the middle winding of relay 242 and elements 264, 265, 266, 267, 58 and 59; consequently, the short-circuit around the middle winding of relay 242 is removed, and this relay is maintained actuated by current flowing in this winding.

Relays 243-246 are locked up in the same way as relays 240-244, consequently, relay 218 (Part 1) cannot be energized again by a calling line, inasmuch as the path through the relay to battery 40 is now open, wire 222 being disconnected from the battery as long as relays 240, 242 and 243 all remain locked up or energized.

Whenever relay 218 is rendered inoperative, as just described, a calling line in the 0000's is enabled to connect the proper numerical signal circuit to an operator's receiver at the third switchboard section. The traced path through contact 46 of relay 34 (Part 1) instead of proceeding by way of contacts 47 or 60 through the upper windings of relays 48 or 218, now proceeds by way of contact 130 through the upper winding of section connecting relay 268, elements 269, 270, 271, 272, 273, 274, 275, 276, 277, 278, 260 and then proceeds by the 130

already traced path to battery 40, energizing relay 268. This gives a shunt path through the left winding of relay 34 and the lower winding of relay 268, elements 279, 5 280, 281, 282, 283, middle windings of relays 284 and 285, 286, 287, 288, 289, 290, 291, 59 and battery 40. Call transfer relay 283 is energized by the current flowing in this path in the same way that the corresponding call 10 transfer relays 67 and 234 of the first and second sections were energized. Dotted line 282 represents the corresponding elements of the third section to those described as being represented by dotted line 233 of 15 the second section. Contact 292 of relay 268 is connected in a corresponding way to contact 239 of relay 218.

Relays 234-283 are shown without a right grounded contact and armature switch 20 such as shown on relay 67, though it will be understood that relays 234-283 have such contacts for the purpose of closing a similar circuit to that controlled by contact 92 of relay 67. Relays 293, 294 and 295, 25 respond in function to relays 166, 181, and 184. Relays 284, 285 and 296 correspond in function to relays 163, 182 and 185. Relays 297, 298 and 299 correspond in function to relays 158, 183 and 186.

30 The third section relays represent another alternative form which may or may not be used for the other described sections as well as for the third one. The use of this form requires less contacts on the relays of the 35 first and second positions. The middle windings of relays 284-285 are such that the current flowing in the traced circuit therethrough which energized relay 283 is not sufficient to cause the energization of relays 284-285, though it is sufficient to maintain them energized once they have been energized by current flowing in the other windings.

When the operator at the first position of 45 the third section answers a call, relays 284-297 are energized or locked up, as described in relation to the corresponding relays 163-158 and 240-244; relays 268-283 being de-energized, as described in relation 50 to the corresponding relays 48-67 and 218-234, thereby making relays 268-283 available for use by other calling lines. The traced path through wire 272 to wire 277, by way of contacts 273-274 of relay 55 284, is opened when the relay becomes energized, but there is still another path available by way of contacts 300-301 of relay 285 and contacts 302-303 of relay 294. Therefore, relays 268-283 can be again 60 energized and the next call will be received by the operator at the second position, inasmuch as the operator's receiver thereat is connected to the signal circuit in the same way as described in relation to the second 65 position of the first section.

When the operator at the second position of the third section answers a call, relays 285-298 are energized or locked up (as described in relation to the corresponding relays 182-183 and 242-245) and relays 70 268-283 are made available for use by other calling lines. The traced path through wire 272 to wire 277 by way of contacts 300-301 of relay 285 is opened when the relay becomes energized, but there is still 75 another path available by way of contacts 304-305 of relay 296 and contacts 306-307 of relay 295. Therefore, relays 268-283 can be again energized and the next call will be received by the operator at the third position, 80 inasmuch as the operator's receiver thereat is connected to the signal circuit in the same way as described in relation to the third position of the first section.

When the operator at the third position 85 of the third section answers a call, relays 296-299 are energized or locked up, as described in relation to the corresponding relays 185-186 and 243-246, and relays 268-283 are again made available for use 90 by other calling lines. However, the traced path through wire 272 to wire 277 is now entirely open, inasmuch as the energization of relay 296 disengaged contact 305 from contact 304 and connected it to contact 308. 95 Therefore, the traced path through wire 269, closed by the next calling line, instead of proceeding by way of contacts 270-271 of relay 283, now proceeds by way of relay 180, wire 309, contacts 308, 305, 306, 307 and 100 wire 277, energizing lock-out release relay 180. The energization of relay 180 causes contacts 178-179 to be disengaged, thereby opening the circuit through the described locking windings of relays 163-158, 105 182-183, 185-186, 240-244, 242-245, 243-246, 284-297, 285-298 and 296-299, consequently, all these relays are de-energized, providing current is not passing 110 through one of their other windings. The de-energization of any one or all of relays 163, 182 or 185 opens the circuit through wire 228; the de-energization of any one or all of relays 240, 242, 243 opens the circuit through wire 277 and the de-energization 115 of any one or all of relays 284, 285, 296 opens the circuit through wire 309. Therefore, if only one of these relays is de-energized the circuit is opened through relay 180 and the latter is de-energized. The 120 traced path through wire 269 and contacts 270-271 of relay 283 is also opened, providing one or all of the last cited second section relays is de-energized, consequently, the calling line signal circuit which was 125 closed through wire 269 is closed instead through wire 219 and contacts 220-221 of relay 284, the call being received in the already described manner by the operator 130 at the first, second or third position of the

second section. However, the path through contacts 220—221 of relay 234 is open also, providing one or all of the cited relays of the first section is de-energized, in which 5 event the calling line signal circuit is closed through wire 49 and contacts 50—51 of relay 67, instead of through wire 219, and the call would be received by an operator at the first section, as already described. Therefore, whenever relay 180 is energized when 10 all the signal transfer relays of all the switchboard sections at which there are operators are energized, the described sequence in which the incoming calls are received by the operators is repeated. It will readily be seen that relay 180 and the described locking windings on the signal transfer relays furnish the means for evenly dividing the calls among the operators on 15 duty, inasmuch as once such a relay is locked up it cannot be de-energized as long as there is a similar relay located after it in order of sequence that is not locked up, the equivalent circuit changes to those produced by this locking up being performed 20 by the removal of an operator's transmitter plug from its jack.

A single call emanating from one of the 0000's has now been traced through to each 30 one of the operators at the switchboard, the calls having been received successively only after the release of the signaling circuit, which is brought about by the insertion of an answering plug in a line jack of the calling line. It is evident that provision must be made for handling simultaneous calls, without delaying them, until such release is made and without confusing the signals. As 35 illustrated and about to be described, arrangements are made whereby as many simultaneous calls may be practically instantaneously put through to the operators as there are switchboard sections at which there are operators on duty. As any 40 probable combination of simultaneous calls will be distributed amongst the various 100's, the selective means illustrated is such that only one line in each 100 can close the described numerical signal circuit at one time, the 45 first line to close said circuit locking out all the other lines of the same 100 until an answering plug is inserted in the proper line jack, whereupon another calling line in the same 100 is enabled to at once sound 50 its signal in the receiver of the next operator ready to receive the same. Inasmuch as only one call can be received by an operator at a time and an operator is only selectable when not otherwise engaged, the 55 only delay incident to attending to the call of the second calling line is that represented by the time it takes the operator to insert the answering plug in the proper line jack after having heard the corresponding signal. 60 It is evident this delay will be insignificant

and only a fraction of the delay now incurred in manual systems where the second calling line must wait until the call has been completed through for the first calling line. Should three or more lines in the 70 same 100 call at the same instant, the calls will be put through correctly and separately to three or more operators as fast as the operators pick up the signals and insert the answering plugs. It will be evident, 75 as the description is proceeded with, that the invention is not limited to this division into 100's inasmuch as the same has merely been chosen to illustrate the invention.

It has already been described how battery 80 cut-off relay 39 (Part 1) is energized whenever any one of the battery control relays 0—9 is energized, consequently, contact 16 of relay 39 disengages contact 15 and engages contact 310. Therefore, should the receiver at another substation in the 0000's, such as 0024, be removed from its switchhook after the receiver at number 0001 has been removed, instead of path being given for current from battery 11, through contact 16 of relay 39, as described, a path is given for induced current from secondary 311 through elements 310, 16, 17, 312, 313, 314, relay (20), left one of terminals (24), substation line and apparatus, other substation line, right one of terminals (24), relay (4) and to ground. The induced current in secondary 311 is produced by the variable current flowing in primary 315 through interrupter 14. Relays (20) and 90 (4) are not energized by the induced current flowing in this circuit as the same need battery current for their energization; however, the induced current flowing through these relays is such that it produces an audible signal in the receiver at substation 0024 which is similar to the one produced by the described variable current flowing through the substation primary direct from interrupter 14. The purpose of the audible signal produced at the substation is for assuring the party thereat that the line wires and central office apparatus are in working order and also for providing a means whereby the discontinuing of the signal, brought about when the operator inserts an answering plug in the line jack, indicates to the calling party that the operator is ready to receive the number of the desired line, thereby allowing the verbal query of the operator to be dispensed with. 110

As no numerical signal circuit is closed until a relay such as (20) or (4) is energized the second calling line does not interfere with the numerical signal produced by 125 the first calling line. As soon as relay 39 is deenergized, when the operator answers the first calling line, battery current flows through relays (20) and (4) by way of contacts 15—16 and, consequently, the relays 130

are energized and the corresponding numerical signal "0024" is produced in the same way as described in relation to the production of the "0001" signal.

5 If two substation receivers belonging to the same 100 are removed from their respective switch-hooks at precisely the same instant, nevertheless, only one of the numerical signal circuits will be closed. Assuming that 10 the two already described numbers 0001—0024 call at the same instant, then, if relays 0 and 2 are energized at precisely the same instant, current will continue to flow through line relay (00) by way of contacts 37—20 15 of relay 0 and relay 39; but current cannot continue to flow through line relay (20) by way of contact 314 of relay 2, inasmuch as the path is opened for current through contact 313 when contact 16 of relay 39 disengaged contact 15, and even if contact 316 of 20 relay 2 had engaged contact 314 before relay 39 was energized, battery current is cut off from contact 316 when contact 37 disengaged contact 317. Therefore, relays (20), 25 (4) and 2 are all de-energized and remain de-energized as long as relay 0 is energized. It will be noted that the battery current through relay 39 is led, by way of contacts such as 37—317 of relay 0, 318—319 of 30 relay 1 and 316 of relay 2, successively to all the relays 0—9 pertaining to the same 100. This is a precautionary detail to prevent the possibility, however slight, of two of the 35 relays being energized and engaging their contacts such as 37—20 of relay 0, at precisely the same instant. As illustrated and described, preference is given to the lowest ten relay when two or more simultaneous calls are received. However, it will be readily 40 understood that the preferential arrangement is purely arbitrary and may be varied as desired.

As soon as the call from line 0001 has been answered, relays 0 and 39 are de-energized 45 and, consequently, path is given for current from battery 11 through elements 12, 13, 14, 15, 16, 17, 312, 313 and 314, thereby causing relay (20) to be energized and closing the circuit through battery control relay 2. 50 When contact 316 of relay 2 engages contact 314 it now maintains relay (20) energized, inasmuch as battery current through relay 39 and contact 37 of relay 0 can now pass by way of elements 317, 318 and 319. 55 Once contact 316 has engaged contact 314, the path therethrough cannot again be opened by the subsequent energization of relays 0 or 1, inasmuch as relay 39 is again energized, thereby preventing the necessary 60 initial energization of relays (00) or (10), which can only take place by means of the current which flows through contacts 15—16 of relay 39. Therefore, it will readily be seen and understood that while preference 65 is given to the lowest number of two or more

simultaneous calls, no preference is given to a lower number if a call is made an instant after a higher number has called. The time between the two calls, which would insure the higher number the first control of the 70 signal circuit, would depend on the rapidity of action of relay 39 and relays (20) and 2. As such relays are very rapid in action, a fraction of a second difference would be sufficient.

75 As the line relays used in the preferred embodiment of my invention are not individual to each line, two lines in the same ten of the same hundred calling at the same time, or one calling before the other was attended to, would permit the current flowing through the ten relay to return to ground through both of the unit relays; for instance, if lines 0000 and 0001 are both calling then a path is given through terminals 80 21—33 of (01), as hereinbefore described, and unit line relay (1) is energized; however, the battery current flowing through ten line relay (00) would also have a path through the left one of the (00) terminals 85 (corresponding to 21—33), apparatus at substation 0000, right one of the same terminals and to ground through relay (0). As the unit relays control the production of 90 the proper numerical signal for the unit numbers, confusion caused by mixing two unit signals is prevented by causing contact 73 of relay (0) to disengage contact 72, thereby opening the circuit traced therethrough from secondary 69 and contacts 70—71 of 100 relay (1), consequently, the "0" unit signal is sounded and not the "1." The order of preference for the unit relays is from the lowest number to the highest, though of course the arrangement illustrated and described is purely arbitrary.

95 In order to insure the proper operation of as many unit relays as may ever be operated at one time through one ten line relay, the winding of the latter may be made of low 110 resistance in comparison to the windings of the unit relays, thereby allowing sufficient current to pass through one ten relay to operate various unit line relays.

115 It will readily be understood, without any further description, that the series of unit line relays (0)—(9), tens line relays (00)—(90) and battery control relays 0—9 are all respectively connected in the described manner, as illustrated in the drawing, thereby positively preventing more than one calling line in each 100 from signaling at the same time, also that each relay connects the proper numerical signal secondary (such as 42 or 69) to the described signal circuits.

120 The terminal rack arrangement shown in the upper part of Part 1 is purely diagrammatical and is used for purposes of illustration only. In practice the wires from the 130

cut-off relay contacts, such as 22—32 of cut-off relay 143, could be taken direct to the proper terminals of the tens and units line relays, instead of to terminals as shown in 5 the drawing. The numbers assigned to the terminals and the connections thereto show clearly how the proper relay is connected to each line.

It is evident that as well as preventing 10 two calling lines in the same 100 from controlling the common numerical signal circuit at the same time, means must also be provided for preventing two calling lines in different 100's from simultaneously producing 15 their respective signals in the same operator's receiver, inasmuch as a plurality of the 100's or all of the same have access to the same operators. The described 100 corresponds to the numbers 0000 to 0099, and 20 in the top row of relays in Part 2 are illustrated section connecting relays corresponding to some of the other 100's in the exchange. Relay 320 corresponds to the next 100 or the numbers 0100 to 0199. Relay 320 25 corresponds in function to and is controlled similarly to relay 48 in Part 1. The section connecting relays for the other switchboard sections, corresponding to 218—268 in Part 1 are not shown, for sake of clear- 30 ness, it being understood that each 100 is equipped with such relays and that the same are respectively installed, in relation to the second and third sections, in the same way that relay 320 is installed in relation to the 35 first section. The upper winding of relay 320 is energized when a call is initiated at any one of the substations of lines 0100 to 0199, the path through the winding proceeding by way of wire 321 to contacts 40 50—51 of relay 67 and thence over the same path as that traced from the upper winding of relay 48 through wire 49 and the same contacts. The consequent energization of relay 320 gives path for current through the 45 lower winding of the relay (as described in relation to the lower winding of relay 48), contacts 322—323, wire 324, contacts 325—62 of relay 48 and thence over the same path as that already traced when contact 62 en- 50 gaged contact 61. Consequently, the same relay (0000) is energized producing the 0 thousand signal; but when contact 326 of relay 320 engages contact 327 it closes a circuit through wire 328 and relay (100) to retardation coil 77, instead of a circuit through wire 76 and relay (000) to the same coil as was closed when contact 75 of relay 48 engaged contact 74. Therefore, the 55 traced path to wire 126, instead of proceeding from the (0) secondary 42 (Part 1) 60 proceeds from the (1) secondary 69 by way of elements 329, 330, 331 and 332, thereby sounding the 100 signal instead of the 000 signal. The ten and unit signal is sounded 65 according to the ten and unit line relays

energized by the calling line, as described in relation to Part 1.

Call transfer relay 67 was energized as soon as contacts 322—323 of relay 320 were engaged, consequently, contact 51 of relay 67 disengages contact 50 and engages contact 68. Therefore, should a line initiate a call in the 0000's or in any other 100, there would be no path for current from battery 40 by way of contacts 51—50 of relay 67, as hereinbefore described; consequently the first section relay, such as 48 or 320 of the 100 in question, could not be energized. However, as contact 68 of relay 67 is connected to contact 226 of relay 227, a path is given for current from battery 40 by way of wire 222 to contact 221 of relay 234. This path through contact 226 is the same as that already traced by way of wires 228—222 when all the relays 163—182—185 had been locked up, when all the relays 166—181—184 had been de-energized, or when one or more of the former had been locked up and one or more of the latter de-energized. Therefore, provided all 90 the operators who might be on duty at the second section are not busy, or all the positions thereat are not vacant, the section connecting relay of the second section of the group containing the call initiating line is 95 energized and the call is put through to an operator at the second section. The path for battery current through wires 228—222 is opened; when all the relays 240—242—243 are locked up, when all the relays 227—241 100—247 are de-energized, or when one or more of the former are locked up and one or more of the latter de-energized; but a path is closed thereby through wires 228—272 to contact 271 of relay 283. Consequently, the 105 call is put through to a third section operator when no second section operator is available. When relay 234 is energized, contact 221 disengages contact 220 and engages contact 333, thereby giving path for current 110 from battery 40 to contact 271 of relay 283 and instantly making the third section selectable by the next calling line of any of the various 100's. This path through contact 333 is the same as that traced hereinbefore through wires 277—272 and the third section relay contacts when there was no available operator at the section section. When relay 283 is similarly energized, contact 271 disengages contact 270 and engages 115 contact 334, thereby connecting battery to wire 269 by way of relay 180; consequently, the next calling line would cause the energization of relay 180, thereby open the circuits through the locking windings of the 120 signal transfer relay and making one or more operators selectable without delaying the incoming call. Relay 180 is of high enough resistance to prevent the actuation 125 of the section connecting relay of the call- 130

ing line when included in circuit therewith, thereby preventing the third section signal circuit from being closed unless relay 283 has been first de-energized.

- 5 It will be seen from the foregoing description that as soon as one call is received in a switchboard section, subsequent calls are locked out from that section and are put through to the next sections, the controlling means being the call transfer relays 67, 234 and 283. However, means must be provided for handling calls from various hundred groups that may simultaneously be initiated at substations. For instance, 10 if a call was simultaneously made in the 0000's and the 0100's and all the operators were free, then the paths through the upper windings of relay 48 (Part 1) and 320 (Part 2) would both be through contacts 50-51 of relay 67, consequently both relays 48 and 320 would be energized. However, when contact 62 of relay 48 disengages contact 325 the path is opened through contact 323 of relay 320, consequently, relay 320 can- 20 not be locked up by current flowing through its lower winding, but relay 48 can be locked up by the current flowing directly through its lower winding from relays 67 and (0000), wire 63 and contacts 62-61. Therefore, as 25 soon as relay 67 is energized and contacts 50-51 disengaged, the path is opened through the upper winding of relay 320 and the latter is de-energized and the section connecting relay corresponding to the sec- 30 ond section is energized instead.

- Relays 335 and 336 represent the first section connecting relays corresponding to the numbers 0600 to 0699 and 0900 to 0999, the dotted lines 337-338 representing the connection of contacts (corresponding to contacts 323-322 of relay 320) of the first section connecting relays of the other hundred groups in the 0000's. Therefore, whenever two or more section connecting relays in the same 40 1000 are energized at the same instant, preference is given in control of the line signaling apparatus of a section to the lowest numbered line and the circuit through the lower or locking winding or windings of the other 45 relay or relays is opened when the top contact of the numerically lower relay disengages its alternate contact. The preferential arrangement shown in the drawing is of course purely arbitrary.

- 50 If the simultaneous calls had been from different thousand groups, then the higher number is locked out in a slightly different manner. Relay 339 represents the first section section-connecting relay corresponding 55 to the numbers 1000 to 1099. The upper winding of this relay is connected to contact 50 of relay 67 by way of wires 340-321 and the relay is energized by said winding in the described manner. However, contact 60 65 341 of relay 339 is connected to wire 64 by

way of thousand signal relay (1000) and contacts 342-343 of relay (0000), consequently, should relays (0000) and (1000) be simultaneously energized, the circuit through relay (1000) and the lower locking 70 winding of relay 339 is opened when contacts 342-343 of relay (0000) are disengaged. As relay 67 remains energized by the current flowing through relay (0000), the second or third section section-connecting 75 relay of the 1000-1099 line is energized and locked up and the call put through to the operator at that section.

For the sake of clearness in the drawing, I have shown but four of the thousand signal relays, namely (0000), (1000), (6000) and (9000). Dotted lines 344-345 represent the connection of contacts, corresponding to 342-343 of relay (0000), of the other thousand signal relays. Therefore, whenever two or more thousand signal relays in a section are energized at the same time, preference in control of the line signaling apparatus of the section is always given to the numerically lower relay and the circuit through the other relay or relays is opened when the bottom contacts of the numerically lower relay become disengaged. At the same time the other call or calls are not delayed, inasmuch as they are at once put 95 through to the other section or sections, the exchange capacity for simultaneous calls depending on the number of sections the switchboard is equipped with, which, of course, should be sufficient to handle the 100 maximum number of simultaneous calls apt to be received.

Contact 346 of first section section-connecting relay 335 is connected by wire 347 to relay (600), consequently, relay (600) is 105 energized whenever relay 335 is energized. As contact 348 of relay (600) is connected by wires 349-350 to secondary 351, which is associated with primary 352 controlled by transmitter 353 which reproduces the "six" 110 signal, the 600 signal is produced in the operator's receiver whenever relay 335 is energized. In the same way the 900 signal is produced whenever relay 336 is energized, inasmuch as contact 354 is connected by 115 wire 355 to relay (900) and contact 356 of relay (900) connected by wires 357-358 to secondary 359, which is associated with primary 360 controlled by transmitter 361 which reproduces the "nine" signal. As 120 the (0000) relay is energized whenever relays 335 or 336 are energized, the proper thousand and hundred signal is given, forming 0600 or 0900, as the case may be. The tens and units signal are supplied by the 125 described line relays.

For the sake of clearness in the drawing, I have shown but four hundred-signal relays, namely, (000), (100), (600) and (900), though it will be understood that the other 130

100's are represented by their respective relays, connected similarly to those described.

First section section-connecting relays 362, 363 and 364 correspond to numbers 1100 to 5 1199, 1600 to 1699 and 1900 to 1999, respectively. Relay (1000) is energized whenever any one of relays 362, 363 or 364 is energized, thereby producing the proper thousand signal, and as the bottom contacts of these 10 relays are connected to relays (100), (600) and (900), respectively, the proper hundred signal is also produced. The other 100's in the 1000's are represented by dotted lines 365—366.

15 First section section-connecting relays 367—368 correspond to numbers 6000 to 6099 and 6900 to 6999, the other 100's in the 6000's being represented by dotted line 369. Contact 370 is connected by wire 371 to relay 20 (6000), thereby producing the proper thousand signal, the bottom contacts of relays 367—368 being connected respectively, to relays (000) and (900), thereby producing the proper hundred signal.

25 First section section-connecting relays 372—373 correspond to numbers 9000 to 9099 and 9900 to 9999, respectively. Contact 374 of relay 372 is connected by wire 375 to relay (9000), thereby producing the proper 30 thousand signal; the bottom contacts of relays 372—373 being connected to relays (000) and (900), respectively, produce the proper hundred signal. Dotted line 376 represents the other relays in the 9000's.

35 It will readily be understood that each switchboard section would comprise ten relays such as (0000)—(9000) and ten relays such as (000)—(900), and that the same would be connected, as hereinbefore described, so as to produce the proper numerical signal. Also that while only three switchboard sections have been illustrated and described, it will be evident that as many more may be added as desired, a relay 40 such as 234 being connected for each section added and a corresponding section-connecting relay and contact on relay 34 added to each 100 for each such section.

The section-connecting relays pertaining 50 to the second and third sections are not shown, but they are connected to contacts 220—270 of relays 234—283, by way of the wires as indicated at 377—378, their connection being the same as the connection of 55 wires 49—321 to contact 50 of relay 67. Dotted lines 283, 282 represent the thousand signal relays, as hereinbefore described.

If at any time and for any reason the line 60 signaling apparatus which produces the "thousand", "hundred", "ten" or "unit" signal should not operate properly, an operator could readily supply the deficiency, providing that three of the four numbers were correctly received, inasmuch as in that 65 event there would only be ten lines to test in

order to locate the calling line. If the "thousand" signal was missing, the operator knowing the correct hundred, ten and unit, would try each one of the corresponding thousands. If the "hundred" signal 70 was missing, the operator knowing the correct thousand, ten and unit, would try each one of the corresponding hundreds. The proper ten or unit could be similarly located.

75 It will be evident that if the calls are received faster than the operators on duty can attend to them, there will be no way the operators can tell whether calls are being inordinately delayed or not, the various section-connecting relays of calling lines merely being non-operative when all the operators are busy. However, it has already been described how lock-out release relay 180 is energized whenever all the position signal 80 transfer relays (such as 163) of the operators on duty are locked up and another call is received; should all these signal transfer relays be energized by means of the circuit traced through their upper windings, (representing the operators engaged in completing calls) then the circuit through relay 180 is not opened when contact 179 disengages contact 178, inasmuch as current would still flow through wire 272 and contacts 271—

95 334. Therefore, relay 180 remains energized and contact 179 engages contact 379, giving path for current from battery 40 through elements 179, 379, 380, 381, 291, 59 and the other pole of battery 40. Lamp 380 may be 100 mounted on the chief operator's desk, so that its constant illumination would constitute a warning signal and indicate to the chief operator that the calls were being received above the capacity of the operators on duty. 105 Therefore, more operators could be sent to the switchboard until the infrequent illumination of lamp 380, its illumination for a very short time, or its non-illumination, would indicate that enough operators were 110 on duty to handle the load. A registering device such as 381, which may be of any desired form, is added to the circuit if it is desired to have a record of the number of times an overload is present. If this device constituted a stylographic register, a permanent record of the time that calls were delayed would be obtained.

115 Contacts 178—379 of relay 180 may be so far apart, that, when some of the position 120 signal transfer relays are locked up and are consequently re-energized when contacts 179—178 of relay 180 become disengaged, contact 179 has not time to engage contact 379 before relay 180 is de-energized by the cutting off of the current through wire 272. Therefore, lamp 380 will only be illuminated and registering device 381 record when there is an actual delay in attending to a call. However, even if contacts 179—379 of relay 130

180 should become engaged, the engagement would be only momentary and lamp 380 and registering device 381 may be such as not to be illuminated and energized by current momentarily passing through them.

As well as relay 180 being kept energized should all the operators on duty be engaged in completing calls, it will remain energized should more calls be simultaneously received than there are switchboard sections available, inasmuch as relays 67, 234 and 283 would all be energized and path would be given for current from battery 40 through wire 52 and contacts 51, 68, 221, 333, 271, 334 of the relays, relay 180, wire 269, and the described apparatus to the other pole of battery 40. Therefore, the repeated illumination of lamp 380 might also indicate that too many simultaneous calls were being received for the operators on duty, consequently more operators could be sent to the board. When all the switchboard positions are occupied, the repeated illumination of lamp 380 would indicate that the capacity of the switchboard was too small.

The chief operator or other official is enabled to know when there are too many operators on duty for the load, as in that case lamp 380 would not be flashing, or by means of an observation of the time interval between any two calls as received by any one of the operators. As the calls are evenly divided amongst the operators on duty whenever one operator is found idle for a longer interval than is standard practice, it would be certain that the calls were not rotating quickly enough among the operators, consequently, some of them could be removed.

The use of manually operated switches such as 176 (as shown at the first section) furnishes means also for determining the load, inasmuch as by opening the switch, position signal transfer relay 163 cannot be locked up and, consequently, the operator at the first position would receive all the calls that could be handled thereat, incoming calls being sent to the other positions only when the first position operator was busy completing a call or receiving a disconnect or recall signal as will be hereinafter described. It will be readily seen that by using switches such as 176 at all the positions, some positions could be allowed to handle all the calls they could handle and other positions allowed to handle their pro rata share only of the remainder.

The second and third positions of the last section of the switchboard may receive fewer calls than the other positions, inasmuch as the other positions may be released from their locked up condition if a call comes in whilst the first position of the last section is receiving a call and before a connection

is made to the line jack. Therefore, these two positions may be used for instructing new operators.

It will be understood wherever condensers are shown for shunting voice currents around relay windings, that non-inductive resistance shunts may be substituted therefor.

From the preceding description, it will be clear that the system is very elastic and capable of many modifications. The described apparatus and means whereby a call initiating line in any hundred group obtains exclusive control of the signal circuit of the group may be used, together with the signal circuit, for producing the line designation of the call initiating line in the receiver of one particular operator, instead of in the receiver of one of a plurality of operators, thereby effecting an economy of apparatus and switchboard space without utilizing the call distributing feature described herein.

Operating conditions sometimes require various kinds of cord circuits to be used at the same or different positions in an exchange, and in Part 3 is shown how this may be done. Link connectors A and B can be used together and C, D and E can also be used together. When the link connector marked B is used instead of the already described link connector A, then when the operator inserts answering plug 382 in a multiple jack 133 or 134 (Part 1), of a calling line, path is given for current from battery 135 through elements 383, 384, 385, 141 or 142 (Part 1), 143 and to ground, energizing cut-off relay 143. The signal circuit of the hundred group and the line signaling apparatus of the section is restored to normal in exactly the same way as hereinbefore described when link connector A was used.

The manipulation of listening key 386 gives path for current from battery 135 through elements 383, 387, 388 and 389 in multiple, upper spring of key 386, 390, 391, 392, 149, secondary of induction coil 150, 94, 117, 151, 393, 394, 395, 396, 397, lower spring of key 386, 398 and to ground, energizing position controlling relay 395, which acts as the controlling means for receiver 94. This closes the already traced circuit through wires 159-162 but by way of wires 399-400 and contacts 401-402 of relay 395, consequently, relays 158-163 are energized and the numerical signal circuit changes are made as described in relation to link connector A.

The operator is enabled to converse with substation 0001, inasmuch as the substation is connected to windings 403-404 of the link connector repeating coil by way of contacts 405-406 of plug 382 and the spring contacts of jack 141 or 142. Voice currents are allowed to pass relay 395 by bridging the same with a condenser 407.

When calling plug 408 is inserted in a

jack of the called-for line, ringing key 409 is manipulated in the usual way. The restoration of listening key 386 to its normal position opens the circuit through relay 395 and the same is consequently de-energized. Relays 158-163 are locked up as described in relation to link connector A.

The insertion of calling plug 408 into a line jack gives path for current from battery 135 through elements 383, upper winding of recall relay 410; 411, 412, 413, 414, 415 and the upper winding of changing relay 416 in multiple; 417, 418, contact of the line jack corresponding to 141 or 142 (Part 2), cut-off relay corresponding to 143 and to ground, energizing the cut-off relay. Relays 410 and 416 are not energized by this current flowing through their upper windings, but ringing lamp 411 is illuminated by the current flowing therethrough. The continued illumination of lamp 411 indicates to the operator that the called-for party has not responded, consequently, the operator periodically manipulates ringing key 409 as long as the lamp remains illuminated.

When a party responds at the called-for substation, the removal of the receiver closes a circuit for direct current through the substation line, in a manner well known in the art. This gives path for current from battery 135 through elements 383, 387, 388 and 389 in multiple, 419, upper spring of key 409, 420, spring contact of jack, one limb of the called-for substation line, substation apparatus, other limb and spring contact of jack, 421, lower spring of key 409; 422, 398 and to ground, energizing calling supervisory relay 389. When contact 415 of relay 389 disengages contact 414, the circuit through ringing lamp 411 is opened, consequently, this lamp is extinguished, indicating to the operator that the called-for substation has answered. When relay 389 is energized, relay 416 is also energized, inasmuch as the shunt circuit around the upper winding of the latter, comprising lamp 411, is opened when contacts 414-415 of relay 389 become disengaged and, consequently, all the current flowing through the upper winding of relay 410 now flows through this upper winding.

Answering supervisory relay 424 was energized when answering plug 382 was inserted in the jack of the calling line, inasmuch as this relay is in circuit with the line of the calling substation. Recall lamps 425-426 are not illuminated, as no appreciable amount of current can pass through contacts 427-428 of relay 424, lamps 425-426, and contacts 429-415 of relay 389, inasmuch as resistance 384 and the upper windings of relays 410-416 are approximately equal in resistance, conse-

quently, lamps 425-426 are included in the bridge arm of a Wheatstone Bridge, the resistances of the cut-off relays being approximately equal.

When the receiver is replaced at either the calling or called-for substation or both, the circuit for direct current is opened through relay 424 or 389 and, consequently, the same is deenergized. This gives path for current from battery 135 through elements 430, 431, right part of winding of relay 432, 433, 434, 435, 436, right winding of relay 437, 438, lower windings of relays 410-416, and 439, 441, 427, 385, 141 or 142, and to ground through the calling line cut-off relay, or 440, 442, 413, 414, 415, 417, 418 and to ground through the called-for line cut-off relay, or through both, energizing relays 432, 437 and 410, and illuminating disconnect lamp 439 or 440, or both. The energization of disconnect relay 437 gives path for current from battery 135 through elements 430, 431, right part of winding of relay 432, 433, 434, 435, 443, 444, 445, 402, 400, 162, upper winding of position signal transfer relay 163, middle winding of induction coil 150 and to ground, energizing relay 163. The energization of relay 163 disconnects operator's receiver 94 from the described line signaling apparatus and connects the latter to the operator's receiver at another position, as has been hereinbefore described. Therefore, an operator is not selectable by a numerical signal circuit whenever there is a link connector in use which should be disconnected. The energization of signal relay 432 causes contacts 446-447 to become engaged, thereby short-circuiting the winding of the relay which de-energizes the same, consequently, contacts 446-447 are disengaged removing the short-circuit and the relay is at once re-energized and the operation repeated. In this manner a vibratory action of armature contact 446 is produced and the resistance of the circuit including the central winding of induction coil 150 (Part 2) varies in accordance with the resistance of the alternately short-circuited winding of relay 432. This produces an alternating current in the secondary of induction coil 150, a path for which is given from the left terminal of the secondary through elements 149, 392, 391, 448, 394, 393, 151, 117 and 94 to the right terminal of the secondary. The passage of this alternating current through operator's receiver 94 causes an audible signal to be produced therein which indicates to the operator that there is a connected line or lines signaling for a disconnect. Illuminated disconnect lamps 439 or 440, or both, would indicate the proper link connector to be removed. Resistance 448 is high enough so as not to appreciably shunt

the voice currents that pass through receiver 94 from the numerical signal circuit or from the link connector repeating coils.

In this way great rapidity in disconnecting the link connectors from idle lines may be obtained, inasmuch as an operator cannot receive an initiated call from a line while there is a connected line signaling for a disconnect, at the same time a positive disconnect signal is sounded in the operator's receiver.

The path traced through relays 432-437 and the lower windings of relays 410-416 to contacts 141 or 142 of the calling line 15 multiple jacks and thence to ground through the cut-off relay, is also affected by the variable current caused by the described short-circuiting of relay 432, consequently, if an operator makes the well known busy 20 test on a called-for line and that line is signaling for a disconnect, instead of hearing the usual click in the receiver, the operator will hear a sustained tone, inasmuch as part of the variable current flowing to ground 25 through the cut-off relay will be diverted through contacts 141 and 142 of the tested jack, contact 421 of calling plug 408 (engaged with the jack contact when the busy test is made), lower spring of ringing key 30 409, contact 422, and repeating coil winding 398 to ground, thereby affecting the operator's receiver which is bridged across repeating coil-windings 387-398 by the manipulation of listening key 386. Therefore, an 35 operator hearing this sustained tone or audible signal when making a busy test would know that the tested line was really idle and that the connecting operator would remove the connected link connector within 40 a moment or so, consequently, the testing operator could wait until the test failed to produce the tone or signal and then would connect to the line in the usual manner. Incoming calls would not be delayed by this 45 action, inasmuch as the testing operator is non-selectable by calling lines as long as a listening key is in its manipulated position. It will be evident that a busy test made on the line connected to the calling plug instead 50 of the answering plug will produce the same busy signal as the variable current has a path through contact 418 of calling plug 408 and the testing contacts of the multiple jacks of the connected line.

If the calling or called-for parties desire a recall, the substation receiver is removed after having been replaced, or the switch-hook is depressed once and then allowed to return to the position it occupies when the 60 receiver is not resting thereon. This would first de-energize supervisory relay 424 or 389 and then re-energize the same. However, recall relay 410 would remain energized, inasmuch as having once been energized by the current flowing through its

lower winding, when relay 424 or 389 is de-energized, it is maintained energized or locked up by the current flowing in its upper or locking winding. Therefore, path would be given for current from battery 70 135 through elements 430, 449, left winding of relay 437, 450, 451, 452; and 425, 428, 427, 385 and to ground through the calling line cut-off relay; or 426, 429, 415, 417, 418 and to ground through the called-for line 75 cut-off relay, energizing relays 449-437. The energization of relay 437 closes the same audible signal circuit as described when a disconnect was signaled. However, the additional energization of operator's recall relay 449 removes the short-circuit around the left part of the winding of relay 432, inasmuch as contacts 434-435 of relay 449 become disengaged; consequently, the increased resistance offered by the entire 80 winding of relay 432 causes a greater variation in the current flowing through the middle winding of induction coil 150 and the audible signal produced in receiver 94 is louder than the disconnect signal. As 85 relay 432 is now energized by a greater number of ampere turns than it was when the disconnect signal was produced, its armature may be so arranged that it will vibrate faster, thereby producing an audible 90 signal of different tone quality, as well as of greater volume. In any event, the operator is enabled to distinguish the recall from the disconnect signal and upon hearing the former would glance over the link 95 connectors in use and locate the recalling line by observing recall lamp 425 or 426 illuminated.

The described disconnect signal circuit through relay 437 is opened when answering plug 382 or calling plug 408, or both, are removed from the line jacks, according to whether the calling or called-for lines, or both, are signaling for a disconnect. Consequently, the disconnect audible signal is only discontinued when there is no longer an idle line to which a link connector is connected.

The described recall signal circuit through relays 437-449 is opened only when calling plug 408 is removed from the line jack of the called-for line, inasmuch as relays 410 and 416 remain energized as long as the calling plug is in a jack, there being a path for current through their upper windings. Therefore, means must be provided for discontinuing the recall signal when it is desired to talk to a line recalling and this is provided for by having relay 395, which is energized whenever a listening key 115 386 is manipulated, open the circuit for both the recall and disconnect signals when contacts 402-445 become disengaged. Consequently, the recall and disconnect audible 120 signals can only be produced in receiver 94 125 130

when the operator is not engaged in talking to a substation or completing a connection therefor.

- The described operation of a disconnect 5 or recall audible signal and the consequent energization of relay 163 changed the connection of the section line signaling apparatus from operator's receiver 94 to another receiver. However, position lockout relay 10 158 which controls the closing of the circuit through the lower or locking winding of relay 163 is not energized when either of these audible signals are sounded, consequently, relay 163 is not locked up and receiver 15 94 is connected again to the section line signaling apparatus as soon as the recall or disconnect audible signal is discontinued. When a listening key is manipulated in responding to a recall, then relay 20 158 is energized and relays 163-158 consequently locked up. As the traced path through relay 449 leads directly to battery 135, there is no variable current flowing through contacts 385 or 418 of plugs 382 25 or 408 when a recall is made. Therefore, a busy test made on a line signaling a recall would produce the well known click and a testing operator would treat the line as busy.
- 30 Should one connected line signal a disconnect and another connected line signal a recall, at the same time or before the link connector was removed from the first line, then relay 449 is energized as soon as the 35 recall is made and the audible signal sounded in operator's receiver 94 would change from the disconnect to the recall. Consequently, the operator would first search for an illuminated recall lamp and 40 would attend to the recall first and to the disconnect afterwards, the disconnect audible signal being reproduced as soon as the recall has been attended to and relay 449 consequently de-energized.
- 45 When a connection is established between two lines by link connector B and the calling line abandons the call previous to the response of the called-for party, path is given for current from battery 135 over the 50 traced circuit through the lower windings of relays 410-416, calling line disconnect lamp 439, contacts 441-427 of relay 424, contact 385 of plug 382, and to ground through the cut-off relay, energizing relays 410 and 416 and illuminating lamp 439. Ringing lamp 411 is consequently extinguished and called-for line disconnect lamp 440 illuminated, when contact 413 of relay 416 disengages contact 412 and engages contact 442. This would indicate to the operator that the link connector should be disconnected and further ringing on the called-for line, after the call has been abandoned by the calling party, is prevented.
- 55 Referring now to link connector C, as

the functions of the same are similar, in most respects, to those of link connector B, only the new features will be described, it being understood that parts shown but not described function the same as corresponding parts in link connector B.

Link connector C requires no listening or ringing keys, operator's receiver 94 (Part 2) being automatically removed from the numerical, disconnect and recall signal circuits 75 whenever an answering plug 453 is inserted in a jack of a calling line, though receiver 94 is not so removed if the plug is inserted in a jack of an idle line. Receiver 94 is again associated with the various signal 80 circuits as soon as a calling plug 454 is inserted in a line jack. Therefore, as well as eliminating the listening keys, an advantage is gained by the fact that the control of receiver 94, in its relation to the signal circuits, is entirely automatic and an operator can only dissociate the receiver from the signal circuits when actually engaged in completing a connection for a calling line.

When a substation has its receiver removed 90 from the switch-hook and answering plug 453 is inserted in a line jack thereof, path is given for current from battery 455 through elements 456, 457, 458, 459, 460, 461, 462, 463, 464, 465, 466 and 467 in multiple, 468, 95 jack contact and one side of line, substation apparatus, other side of line and jack contact, 469, 470, 471, 472, 473, 474, 475, 476 and to ground, energizing position controlling relay 460 and answering supervisory 100 relay 467. The described path through wires 159-162 and 399-400, which was closed by the engagement of contacts 401-402 of relay 395, is now closed through wire 159, 478, 479, 480 and 162; consequently, relays 105 158-163 (Part 2) are energized, as described, and receiver 94 is removed from the section line signaling apparatus and the latter is connected to another receiver. Answered call recording meter 478 is also 110 energized and the call recorded thereon. Inasmuch as relay 460 can only be energized when an answering plug is inserted in a jack of a calling line, meter 478 furnishes an accurate record of the calls answered at any 115 one operator's position.

Relay 460 may be bridged by a condenser 482, so as to allow the passage of voice currents through repeating coil windings 459-476. The operator is enabled to converse with the party at the calling substation, as the path including receiver 94 through wires 149-151 is permanently closed through the operator's repeating coil windings associated with windings 459-476.

A busy test is provided for, inasmuch as when tip contact 485 of calling plug 454 is touched to the sleeve contact of a jack of the tested line, half is given to ground through elements 485, 486, 471, 472, 473, 125 130

474, 475 and 476. Consequently, the busy signal is heard in the operator's receiver on account of it being in circuit with the operator's repeating coil winding associated with 5 winding 476.

- When calling plug 454 is inserted in a jack of the called-for line, half is given for current from battery 455 through elements 487, upper winding of recall relay 488, 489; 10 490, 491, 492, 493, 494, 495, and upper winding of changing relay 496 in multiple relation; 497 and to ground through the cut-off relay of the called-for line, energizing relays 489-490 and illuminating ringing lamp 491. Relays 488-496 are not energized, the former because the current that can pass through its upper or locking winding is only sufficient to maintain it energized after it has been energized by current flowing 20 through its lower winding and the latter because it is shunted by ringing relay 490 and lamp 491. Contacts 498-499 of operator's set relay 489 first engage contacts 464-472 and afterwards disengage the latter 25 from contacts 463-473, thereby substituting, without a break, current from battery 455 to the calling line by way of windings 470-500 of the link connector repeating coil, for current from the same battery by way of 30 the operator's repeating coil. Contact 501, shown connected to winding 470, may or may not be used, its use short-circuits repeating coil winding 470 when the calling line is connected to the operator's repeating 35 coil, thereby avoiding the retarding effect on the voice currents of the winding 470, the short-circuit being removed when contact 472 is disengaged from contact 473. As current now ceases to flow through relay 40 460, it is de-energized and operator's receiver 94 is again associated with the section line signaling apparatus whenever the circuit is opened through the locking winding on relay 163.
- 45 The energization of ringing relay 490 causes ringing current to be impressed on the called-for line, path being given from generator 502 through elements, 503, 504, 505, 506, 507, 508, one side of line, substation call-bell and condenser (as shown at 509-510, substation 10, in part 1), other side of line, 485, 486, 471, 472, 499 and to ground. Between the impressions of ringing current as impressed on the line by 55 way of interrupter 504, an intermittent path is given for direct current from battery 511 through elements 512, 513, 514, 515, 516 and 517 in multiple, and thence over the already traced path through contact 508 of 60 plug 454. However, relay 517 is not energized, inasmuch as the circuit through call bell 509 and condenser 510 does not allow energizing current to pass. Before brush 513 engages the metallic portion of interrupter 512 and after the metallic portion

of interrupter 504 has disengaged brush 503, the line is grounded through wire 505, interrupter 504 and brush 518, thereby removing any static charge that may be left in condenser 510 and the line, before a 70 path is given for the same through relay 517, interrupter 512 and battery 511. Due to this discharge of the line before battery current is connected to the relay 517, there is no possibility of energizing the relay by a static discharge therethrough. Brush 503 engages the center of the metallic portion of interrupter 504 at the precise instant that the positive or negative alternation of the current furnished by alternating current generator 502 is at its apex, consequently, that part of the alternating current that is impressed on the line is always the highest voltage portion of the current. Interrupters 504-512 are preferably insulated from, but mounted on, the shaft of generator 502 or geared thereto so as to revolve in synchronism therewith. As the three circuits, to generator 502, ground and battery 511, are all closed and opened twice for each revolution, in order to have each circuit closed the same length of time, brushes 503-518 should be a distance apart equal to one sixth of the circumference of interrupter 504 or 60 degrees, and the metallic portion of the interrupter should be such that it just escapes bridging the two brushes when passing from one to the other, as shown in the drawing. Brush 513 of interrupter 512 should also be in such position 100 in relation to the metallic portion of interrupter 512 that they become engaged as soon as brush 518 disengages the metallic portion of interrupter 504, as also shown in the drawing. Therefore, if the position of 105 brush 513 corresponds to or is directly opposite to brush 518, the center of the metallic portions of the interrupters would be sixty degrees apart and they would be of the same width. It will be evident that the metallic portion of interrupter 512 may be made larger, the metallic portion of interrupter 504 made smaller and brushes 503-518 placed closer together, thereby closing the direct current circuit for a longer time 110 than the ringing or discharging circuits. For a more complete description of this ringing system reference is to be had to my aforementioned patent and co-pending applications. The only feature claimed herein 115 as new being the particular form of interrupters 504-512.

When a party at the called-for substation responds and removes the receiver, the described direct current path is closed; call-bell 509 and condenser 510, being shunted by a low resistance path. This gives a path 125 for the intermittent current through supervisory relay 517, which energizes the same. As soon as contacts 494-495 become dis- 130

engaged, the described path through ringing lamp and relay 491—490 is opened, consequently, relay 490 is de-energized. Before contact 514 disengages contact 515 the latter becomes engaged with contact 519, consequently, before the path to battery 511 is opened another one is closed by way of repeating coil winding 520 and wire 487 to battery 455. Contact 506, disengaging contact 507, disconnects the ringing current from the line. The extinguishing of ringing lamp 491 indicates to the operator that a response has been obtained.

Relay 488 corresponds in function to relay 410 and relay 496 corresponds in function to relay 416 in link connector B. Relay 496 is energized when the shunt around its upper winding, comprising relay 490 and lamp 491, is removed when relay 517 was energized.

When a disconnect is signaled, path is given for current from battery 455 through elements 456, 521, 522, 523, 524, 525, lower windings of relay 488—496 and thence to ground through the cut-off relay over the described path, energizing operator's disconnect relay 524, and relay 488. This gives path for current from battery 455 through elements 456, 521, 522, 523, 526, 527, 528, 529, 530, 480, 481, 400, 162, 163, middle-winding of induction coil 150 and to ground, energizing relay 163. As interrupter 523 is shunted by a resistance 531, it furnishes a variable but not an intermittent current, consequently, the operator receives the disconnect signal in receiver 94, as described in relation to link connector B. A busy test made on the line signaling the disconnect will produce the same sustained signal, inasmuch as the circuit through relay 524 is to the same interrupter.

When a recall is signaled, path is given for current from battery 455 through elements 456, 457, 532, 533, 534, 535, 536 and thence to ground through the cut-off relay over the described path, energizing operator's recall relay 532. Consequently, contact 529 disengages contact 528 and engages contact 537, which is connected to generator 538. As generator 538 is adapted to furnish a variable current different to that furnished by interrupter 523, the operator is enabled to distinguish between the disconnect and recall signals. It is evident that a battery interrupter such as 523 could be used in place of generator 538 or that a generator furnishing a similar variable current to interrupter 523 could be used instead of the latter.

As the path for both the disconnect and recall signals is opened when contacts 480—530 of relay 460 become disengaged, these signals cannot be sounded when the operator is actually engaged in completing a connection for a calling line or answer-

ing a recall. The recall takes precedence over the disconnect signal, inasmuch as contact 529 of relay 532 disengages contact 528 whenever a recall is made.

An operator's set relay 489 remains energized as long as a calling plug remains in a jack, means must be furnished for de-energizing the same when a recall is made by the calling line in order that the operator's set may be connected to the line re-calling. As means are only provided for talking to the calling line, calling plug 454 may be removed from the line jack thereby de-energizing relay 489, but as the recall may be for the same line it would be necessary, in that event, to re-insert the calling plug in the same jack. To avoid this, a key such as 539 may be used which when manipulated shunts relay 489 and the upper winding of relay 488, by a path through elements 540, 536, 535, 534, 533, 532, 457, 456. The resistance of relay 532 is so low that this shunt does not allow enough current to flow through relays 489—488 to maintain them energized, consequently the operator's set is telephonically connected to the calling line as long as key 539 is in use. If calling plug 454 is not removed from the line jack, the release of key 539 will cause relay 489 to be re-energized, but relay 488 will not be re-energized until its lower winding receives current again. If recalls from the called-for line are to be attended to by the connecting operator, the calling plug is removed from the jack and an answering plug of another link connector may be inserted.

The manipulation of key 539 previous to a disconnect or recall being signaled will not cause relay 489 to be de-energized, inasmuch as the shunt path would be open at contact 536 of relay 488, the latter only being energized when a disconnect is signaled. Therefore, it is impossible for an operator to "listen in" on a conversation passing through the link connector, the operator's set being connectable thereto only when it is not being used for conversing between substation lines.

When the calling party abandons a call previous to a response at the called-for substation, relay 496 is energized by the disconnect circuit through its lower winding and ringing relay 490 is de-energized when contacts 492—493 are disengaged. Therefore, ringing current is not further impressed upon the called-for line.

Referring now to link connector D, the principal difference between this form and that shown at C is that means are provided whereby if a recall is made by the called-for line, the functions of the answering and calling plugs may be reversed and the line asked for rung by inserting the answering plug in a jack thereof, thereby avoiding the

necessity of removing the calling plug from the jack of the recalling line and substituting an answering plug therefor. As well as this feature, means are shown whereby 5 non-inductive resistances 541—542 are not bridged around supervisory relays 543—544 until after the relays have been energized and means are provided to allow the operator to converse, with either the calling or 10 called-for line when a recall is made, without disturbing the link connector connections.

When answering plug 545 is inserted in a jack of the calling line, the traced path 15 through relay 460 by way of wire 461, instead of proceeding by way of contacts 463—464 of relay 489 of link connector C, proceeds by way of elements 546, 547, 548, 549, 550, 551, 552, 543, and 553, 554, 555, 556, 541, 20 in multiple therewith; 557, one side of line, substation apparatus, other side of line, 558, 559, 560, 561, 562, 563, 564, 475, 476, and to ground. Operator's receiver 94 is removed 25 from association with the section line signaling apparatus by the energization of position controlling relay 460 and the operator can converse with the party at the calling substation as not only is winding 550 of the link connector repeating coil in series 30 with winding 459 of the operator's repeating coil, but winding 550 and supervisory relay 543 are both shunted by non-inductive resistance 541. The path for this shunt from wire 547 is by way of elements 548, 35 549, 565, 555 and 556; consequently, the retarding effect on the voice currents of repeating coil winding 550 and relay 543 are overcome. Repeating coil winding 559 can be short-circuited by having contact 561 of 40 relay 579 engage contact 582 connected to winding 559.

Supervisory relay 543 may not be energized by the current flowing through it on account of the described shunt through non-inductive resistance 541, in which event path 45 is given for current through disconnect relay 524 and elements 566, 567, lower windings of relays 568—569, 570, 571, 572, 573, 574, and to ground through the cut-off relay, energizing relays 568—569. The consequent disengagement of contacts 553—554 does not affect the passage of the voice currents through non-inductive resistance 541, inasmuch as the path through contacts 55—548 of relay 579 is understood. 55

When calling plug 575 is inserted in a jack of the called-for line, path is given for current from battery 455 through elements 456, 521, 576, 577, 578, 579; 580 and upper winding of relay 569 in multiple and thence by way of contact 581 to ground through the cut-off relay, energizing relays 579—580. (Relays 580, 569, 544 correspond to relays 490, 496, 517, respectively, as shown and described in relation to link connector C and,

therefore, need not be further described.) When contact 583 of relay 579 engages contact 549 it disconnects contacts 548—565, consequently, the described shunt around relay 543 through resistance 541 is opened and 70 as contact 583 is connected by way of wires 578, 577, 576, 521 and 456 direct to battery 455, relay 543 is energized, the disengagement of contacts 572—573 opening the described circuit through the lower windings 75 of relays 568—569 and de-energizing the same. This causes contacts 553—554 of relay 568 to become engaged closing the shunt circuit again around relay 543 through resistance 541. However, relay 543 is maintained energized, as it was energized first before the shunt path was closed. Repeating coil winding 584 is also connected to battery 455 when contact 583 of relay 579 engaged contact 549; contact 585 connecting 80 ground to windings 559—586 by way of contact 561 and removing the short-circuits around these windings through the contact connected by dotted line. The operator's repeating coil is disconnected from the link 85 connector, after this battery connection has has been made when contacts 548—549 and 561—562 become disengaged.

Wire 587 would connect to brush 513 of interrupter 512 and wire 588 corresponds to 90 wire 505 which is connected to interrupter 504. Therefore, path is given for ringing current through elements 588, 589, 590, 542, 591 to the called-for line and path is given for the intermittent battery current through 100 elements 587, 588, 599, 544 and 591. Consequently, relay 544 is energized by the full force of the intermittent battery current that flows over the called-for line, inasmuch as its winding is not shunted by non-inductive resistance 542.

When a response is obtained at the called for substation and ringing relay 580 is de-energized, contact 590 after disengaging contact 589, thereby disconnecting the ringing 110 current, engages contact 600 and shunts non-inductive resistance 542 around the winding of supervisory relay 544, the path being by way of contacts 601—602 of relay 568.

When a disconnect is signaled by either 115 line, path is given as described through the lower windings of relays 568—569 and operator's disconnect relay 524, thereby causing the described disconnect signal to be given.

When contacts 553—554 and 601—602 become disengaged, non-inductive resistance shunts 541—542 are removed from around supervisory relays 543—544. This allows the full force of the current which flows over the lines to be used for re-energizing 125 the supervisory relays should a recall be made. Relay 568 remains locked up after the opening of the disconnect circuit, inasmuch as path is given for current from battery 455 through repeating coil winding 584, contacts 130

602—603, upper winding of relay 568, upper contact and spring of key 604, and to ground through the cut-off relay by way of the traced path through relay 569.

5 When a recall is signaled, path is given through operator's recall relay 532, wires 533, 605, 606 and contact 607 of relay 568, the path proceeding as already amply described in relation to the other link connectors.

10 Key 604 corresponds to key 539 in link connector C. When this key is closed the path is opened through the upper winding of relay 568 and relay 579 is de-energized on account of the described low resistance shunt through operator's recall relay 532. As the operator's telephone set is connected to both the calling and called-for line repeating coil windings, the operator is enabled to converse with either line or with both. Repeating coil winding 584 and supervisory relay 544 are shunted by non-inductive resistance 542 by way of elements 590, 600, 608 and 549, thereby overcoming their retarding effect on voice currents to and from the called-for line. A key such as 609 may be provided to use when the calling line recalls and desires another connection to the same called for line. The closing of this key

20 short-circuits the upper winding of relay 569 and, consequently, causes the relay to be de-energized. This energizes ringing relay 580 again and the call-bell at the called-for substation is rung again. Key 609 need only 30 be closed momentarily, inasmuch as the shunt through relay 580 keeps relay 569 from being re-energized. The improper closing of key 609, when the called-for line had not yet signaled a disconnect, would not 40 de-energize relay 569 on account of the key being connected to contact 610 of supervisory relay 544, this contact being disengaged from contact 611 until the relay is de-energized when the called-for line signals a 45 disconnect. Contact 612 of relay 569 is connected to the lower terminal of the lower winding of the relay, instead of to the upper as shown in link connectors B and C, so that the relay is not energized by current flowing

50 through the lower winding when supervisory relay 544 is de-energized and supervisory relay 543 is energized, as would be the case when the calling line recalls for the called-for line. If the recall is from the called-for line, it is not necessary to remove calling plug 575 from the jack and substitute an answering plug therefor in order to be able to ring on the desired line. Answering plug 545 is inserted in the proper jack, or allowed to remain in the same jack if the desired line is the formerly calling one, and key 613 is closed, giving path for current from battery 455 through elements 456, 521, 576, 577, 614, lower winding of ring-back relay 615, 613, 572, 573, 574 and to ground

through the cut-off relay energizing relay 615. The path through the lower winding of relay 568 is opened when contacts 570—571 of relay 615 are disengaged and as the upper winding of relay 568 is still de-energized, on account of the upper contact of key 604 being disengaged from the key spring, contacts 601—602 are engaged and battery current passes therethrough and through ring-back lamp 616, upper winding 70 of relay 615, alternate contact and contact 571, contacts 572—573 of relay 543, plug contact 574 and to ground through the cut-off relay. This maintains relay 615 energized so that key 613 need only be closed momentarily. Contact 556 disengages contact 555 and engages contact 617, thereby disconnecting non-inductive resistance 541 from either of the repeating coils and connecting it to wire 588 which would lead to ringing interrupter 504, 80 consequently, ringing current is impressed on the line through answering plug 545. Contact 618, which is connected to wire 587 which would lead to intermittent battery interrupter 512, engages contact 552 first 85 and then disengages the latter from contact 551, thereby connecting supervisory relay 543 to the intermittent battery interrupter.

When the called-for substation responds, supervisory relay 543 is energized and when 95 contacts 572—573 are disengaged the path is opened through the upper or locking winding of relay 615, consequently, the circuits controlled by this relay are restored to their normal condition and the two substations 100 can converse with each other. Should the recalling substation connected to calling plug 575 abandon the call previous to the response of the called-for substation connected to answering plug 545, then the described disconnect circuit is closed through the lower winding of relay 568 and the consequent disengagement of contacts 601—602 opens the circuit through the upper winding of relay 615, 105 thereby discontinuing the impression of ringing current and restoring the circuits controlled by relay 615 to their normal condition.

Referring now to link connector E, the principal difference between this form and 115 that shown in link connector C, is that means are provided whereby the busy test may be dispensed with and the operators connect to the called-for lines regardless of whether they are busy or not. If the line is busy, 120 telephonic connection is not established until the line becomes idle, ringing current being thereupon impressed on the line. At the same time that the connection is made to a busy line a busy signal is sounded in 125 the calling substation receiver, so that the calling party is informed of the busy condition of the line called for. If the calling party does not care to wait, the receiver is replaced, the operator signaled to discon- 130

nect and ringing current prevented from being impressed on the called-for line when it becomes idle. Means are also provided whereby an audible signal is sounded in the operator's receiver if a connection is made to a line which is not only busy but with which one of the described waiting connections has been established, thereby allowing the operator to so inform the calling party and 10 to withdraw the calling plug from the line jack. If desired, means may be provided whereby a plurality of calling parties may wait on the one called-for line, as shown and described in my aforementioned application No. 45,232, to which reference is 15 to be had for a more complete description and modified forms of the special means used to obtain the described results. Means are also shown whereby an operator is prevented 20 from establishing a telephonic connection to a busy line by way of an answering plug, though the relay that performs this function may be eliminated without disturbing the function of the other described means. 25 For sake of clearness in the drawing, link connector E is modelled on C, though it could be modelled on D. Any parts shown and not described will be understood to correspond in function to similar parts 30 already described in relation to link connector C.

When answering plug 622 is inserted in a jack of a calling line, path is given for current from battery 623 through elements 35 624, 625, 626, 627, 628, 619, 629, 630, 631 and to ground through the cut-off relay, intermittently energizing relay 619 on account of the intermittent current allowed to pass through interrupter 626. This intermittent energization need only be sufficient to cause contact 632 to engage contact 628, interrupter 40 626 being thereby shunted by a direct path to battery 623; consequently, the steady current sustains relay 619 energized, causing contact 628 to become disengaged from contact 627, thereby disconnecting interrupter 626 from the relay. This gives path 45 for current through the operator's repeating coil and relay 460, elements 461, 546, 50 633, 634, 635, 636, 637, 638, 639 and 640 in multiple, 641, jack contact and one side of line, substation apparatus, other side of line and jack contact, 642, 643, 644, 645, 646, 647, 648, 563, 564, 475, 476 and to 55 ground, energizing relays 460—640 and connecting operator's receiver 94 to the calling line.

When calling plug 649 is inserted in a jack of the called-for line, path is given from battery 623 through elements 624, 625, 650, 651, 652, lower winding of relay 621, 653 and upper winding of relay 654 in multiple, and thence by way of contact 655 to ground through the cut-off relay, intermittently 60 energizing relay 621 on account of the inter-

mittent current allowed to pass through interrupter 650. (Relays 653, 654, 656 correspond to relays 490, 496, 517, respectively, as shown and described in relation to link connector C and need not be further 70 described.) This intermittent energization of relay 621 need only be sufficient to cause contact 657 to engage contact 652, interrupter 650 being thereby shunted by a path through contact 657, upper winding of relay 658 and 75 wire 624 direct to battery 623; consequently, the steady current sustains relay 621 energized, causing contact 652 to become disengaged from contact 651, thereby disconnecting interrupter 650 from the relay. 80 Recall relay 658 is not energized by the current flowing through its upper winding, inasmuch as this relay functions the same as relay 488 in link connector C. Contacts 85 659—660 of operator's set relay 621 first engage contacts 636—645 and then disengage the latter from contacts 635—646, thereby substituting, without a break in the circuit, current from battery 623 through link connector repeating coil windings 661—662 90 for current from battery 455 through the operator's repeating coil. (It will be understood that batteries 455 and 623 may be the same battery, being shown separate for sake of clearness in the drawing.)

The insertion of the calling plug also gives path for current from battery 623 through elements 624, 625, 626, 663, 664, 665, lower winding of relay 620, 666, 667, 655 and to ground through the cut-off relay, intermittently energizing relay 620. This intermittent energization need only be sufficient to cause contact 668 to engage contact 665; interrupter 626 being thereby shunted by a direct path to battery 623; consequently, the steady current sustains relay 620 energized, causing contact 665 to become disengaged from contact 664, thereby disconnecting interrupter 626 from the relay. Ringing relay 653 is maintained energized as soon as steady current flows through relay 621, consequently, path is given for ringing current from generator 669 through elements 670, 671, 672, 673, 674, 675, 676, 677, jack spring and one side of line, substation call bell and condenser, other side of line and jack spring, 678, 679, 680, 646 and 681 (engaged when relay 621 was energized), 682 and to ground. At the same time path 100 is given for the intermittent battery current from interrupter 683 through elements 684, 685, 656 and 686 in multiple, 674 and over the described path to the called-for substation. (Interrupters 670—683 represents a modified form of interrupters 504—105 512 shown in link connector C, there being no means for discharging the line to ground and the battery impressions being longer than the current impressions on account of the larger metallic portion of interrupter 110 681.)

683. It will be understood that the form as used with link connector C might be used with link connector E). When the called-for substation responds and ringing relay 5 653 is de-energized, as described in relation to link connector C, contact 685 becomes engaged with contact 687, thereby connecting supervisory relay 656 and non-inductive resistance 686, by way of contacts 687, 10 635 and 688 (engaged when relay 621 was energized), to repeating coil winding 689. When relay 619 was energized, upon the insertion of answering plug 622 in the line jack, path was given for current from battery 15 623 through elements, 624, 625, 690, 691, 692, upper part of winding of relay 619, 629, 630, 631 and to ground through the cut-off relay. The upper part of this winding is of very low resistance, so that 20 whenever the metallic portion of interrupter 690 engages its brush, the lower or higher resistance part of the winding is shunted through the interrupter. However, the current passing through the upper part of the 25 winding maintains the relay energized, but should another answering or calling plug be inserted in another jack connected to the same cut-off relay, the relay corresponding to 619 or 620 would not be initially energized by the described intermittent current 30 from interrupter 626, inasmuch as interrupters 626—690 both connect the same battery current at the same time to the low resistance winding of relay 619 and the higher resistance complete winding of the other relay 35 corresponding to 619 or 620. Consequently, most of the current allowed to pass through the cut-off relay would follow the low resistance path and not enough would follow 40 the higher resistance path to intermittently energize the other relay. As the upper contacts of relays 619—620 do not close the paths through the tip and ring contacts of the answering and calling plugs until 45 after the relays are maintained energized by the described steady current, it will be seen that no telephonic or ringing connection can be established to a busy calling line.

When relay 620 was energized, upon the 50 insertion of calling plug 649 in the line jack, path was given for current from battery 623 through elements 624, 625, 690, 693, upper winding of relay 620, 694, 695, 666, 667, 655 and to ground through the cut-off relay. 55 This upper winding is also of very low resistance; consequently, while relay 620 is maintained energized, another relay 620 or 619 of another link connector connected to the same line will not be initially energized 60 by the intermittent current from interrupter 626, due to the low resistance shunt through this upper winding. Therefore, if it was an answering plug that was inserted by mistake in the line jack, the operator would obtain 65 no response and would know that a connection had been made to a busy or a non-calling line. If it was a calling plug that was inserted in the jack of the busy line, operator's set relay 621 would nevertheless be energized, inasmuch as it is not affected by the 70 described low resistance shunt circuits, the metallic portion of interrupter 650 engaging its brush at a different time interval than interrupters 626—690. Therefore, the operator's telephone set is disconnected from the 75 link connector and the operator would not know whether the connected line was a busy line or not, inasmuch as no busy test has been made. However, as relay 620 is not energized, path is given for a part of the current 80 flowing from battery 623 to ground through the cut-off relay from the first connected link connector, by way of contact 655 of calling plug 649, elements 667, 696, 697, 680, 646, 681, 682 and to ground. As the current flowing to the cut-off relay from the first connected link connector is a variable one, due to the intermittent lowering of the circuit resistance when the metallic portion of interrupter 690 engages its brush, repeating 85 coil winding 682 is affected thereby and by inductive means reproduces an alternating current in the associated winding 662 which is in series with the calling substation line. Therefore, an audible busy signal is sounded 90 in the substation receiver and continues to be sounded therein as long as the called-for line remains busy. Resistance 696 is used 95 when repeating coil winding 682 is of a low resistance, in order not to give path to too 100 much current, and may be in inductive relation to repeating coil winding 682, as shown; if it is in inductive relation thereto it augments the strength of the alternating current produced in winding 662. On hearing the 105 audible busy signal the calling party may wait for the line to become idle, or may replace the substation receiver, thereby sounding the described disconnect signal in operator's receiver 94, de-energizing ringing relay 653 and, consequently, preventing the impression of ringing current on the busy line when it becomes idle, and also making the connecting operator non-selectable by a calling line. If the calling party waits, then as 110 soon as the first connected link connector is removed from the line jack, the described low resistance shunt is removed from around the winding of relay 620 and it is at once energized, ringing current being impressed 115 on the line and the connection completed as already described. When contact 680 of relay 620 disengages contact 697 the busy signal ceases to be sounded in the calling substation receiver and the ringing signal 120 is sounded instead, inasmuch as the return path to ground for the ringing current is by way of repeating coil winding 682. Therefore, the calling party is advised of the fact 125 that the line is now idle, is being rung and 130

will be telephonically connected to the calling substation when a party at the called-for substation responds.

Previous to the busy line becoming idle 5 and while the second connected link connector was connected thereto, should another link connector be connected to still another jack of the same line, then operator's set relay 621 of the third connected link connector 10 is not energized. This is brought about by means of a low resistance shunt circuit that would be closed in the second connected link connector, giving path to current from battery 623, through elements 624, 625, 698, 699, 15 700, upper winding of relay 621, 701 and 695 (relay 620 not being energized), 666, 667, 655 and to ground through the cut-off relay. The metallic portion of interrupter 698 engages its brush during the same time 20 interval that the metallic portion of interrupter 650 engages its brush, consequently, sufficient current cannot pass through the lower winding of relay 621 of the third connected link connector to cause contact 657 to 25 engage contact 652 and the relay is not intermittently energized as hereinbefore described. Contacts 659-660 do not engage contacts 636-645 until the relay is fully energized by steady current, consequently, the 30 operator's set remains connected to the link connector and the described variable current which produces the busy signal instead of proceeding through contacts 646 and 681 to the link connector repeating coil, proceeds 35 instead through contacts 646 and 647, wires 648, 563, 564, 475, to ground through winding 476 of the operator's repeating coil. Therefore, the busy signal would be sounded in operator's receiver 94 and the operator 40 would know that there was already a calling party waiting for the line to become idle and would remove the third connected calling plug from the jack and notify the calling party.

45 Notwithstanding the fact that no busy test is required, if the same is desired, an extra contact 702 is added to operator's set relay 621 and the same is connected as shown. This gives path through tip contact 678 to grounded winding 476 of the operator's repeating coil when a busy test is made and causes the proper busy signal to be sounded in operator's receiver 94.

The recall and disconnect features of link 55 connector E are the same as described in relation to link connector C.

Reference is to be had to my aforementioned co-pending application No. 64,967, for a description of similar forms of link 60 connectors which may easily be adapted for use with the described call distributing equipment.

Referring now to Figure 2: Relay 67' represents the hereinbefore mentioned modification of relay 67 in Figure 1, Part 2.

When this form is used, brushes 82-85-88 of interrupter 81 (Figure 1, Part 1) are common to all the switchboard sections, instead of individual to each section. Inasmuch as the upper terminals of relays 70 90-87-84 are not connected together until relay 67' has been energized, there is no shunt path available for current through relays 90-87-84 of a section where relay 67' is not energized.

75 Referring now to Figure 3: From the foregoing description it will be readily seen and understood that any operator can be rendered non-selectable by a call initiating line if means are provided for energizing position-signal-transfer relay 163, 182 or 185, (Figure 1, Part 2) or the corresponding relays of the other sections. This fact can be taken advantage of to combine the call distributing feature with an answering 85 jack system, when the described call distributing system is installed in an exchange where the substation lines already terminate in answering jacks at the switchboard, or where it is desirable to have some substation lines, such as the busiest lines, given access to the call distributing apparatus; while other lines, such as residence or seldom used lines, terminate directly at answering jacks 90 at one particular operator's position.

95 In Figure 3, B' represents link connector B in Figure 1, Part 3 and relay 143 represents the same cut-off relay as shown connected to substation 10 in Figure 1, Part 1. Relay 703 is an individual line relay which 100 is energized whenever the substation receiver is removed from its switch-hook, giving path for current from battery 704 through elements 705, 706, 707, 708 and to ground, energizing line lamp 706 and pilot relay 705. 105 Lamp 706 is the individual line lamp mounted with the associate answering jack at an answering operator's position. Pilot relay 705 is common to all the line lamps at the same position.

110 Relay 709 corresponds to operator's disconnect relay 437 of link connector B in Figure 1, Part 3. A normally engaged contact with the armature switch of said relay has been added thereto. Therefore when battery current is allowed to pass through this contact, relay 163 is energized in the same manner as hereinbefore described in relation to a disconnect signal from a line connected to a link connector. The use of 115 the described line and pilot relays and the line lamp is well known. However, instead of the energization of pilot relay 705 energizing a visual pilot signal whenever a line lamp is energized, it gives path for current from battery 704 through elements 710, 711, 712, 713, 714, 715 and thence by way of the described path through contacts 445-402 of relay 395 or contacts 528-529 of relay 532 (Figure 1, Part 3), wires 400-162, re-

120 125 130

lay 163 and middle winding of induction coil 150 (Figure 1, Part 2) and to ground, energizing relay 163. This removes operator's receiver 94 from association with the 5 numerical signal circuit and prevents an operator from being selected by a call initiating line which has access to the call distributing apparatus, and instead connects another operator's receiver to the signal circuit. Therefore, whenever an operator receives a call from a line connected to an answering jack at that operator's position, the operator is non-selectable by a line connected to the call distributing apparatus, 10 but the operator is selectable by such a line whenever there is no call unattended from any of the lines connected to answering jacks at that operator's position.

As interrupter 710 furnishes a variable 20 current which is distinct in character from the described disconnect or recall audible signal current, an audible line pilot signal is sounded in operator's receiver 94 whenever pilot relay 705 is energized, the middle 25 winding of induction coil 150 being affected by the variable current and the signal produced, as described hereinbefore in relation to the disconnect and recall audible signals.

Relay 716 corresponds in function to relay 152, associated with link connector A in Figure 1, Part 3. As link connectors A and B may be used together A' in Figure 3 also shows the connections for link connector A.

Relay 717 corresponds to pilot relay 705. 35 The lower winding of relay 716 is connected in the same way as the winding of relay 152 and the contacts close the same circuit. Interrupter 710 is not used when link connector A is used, contact 718 of relay 717 40 being connected direct to battery 704. Consequently, when pilot relay 717 is energized, path is given for current from battery 704 through elements 718, upper winding of relay 716, 719 and to ground, energizing relay 716 and pilot lamp 719. The energization 45 of relay 716 removes operator's receiver 94 from association with the numerical signal circuit and connects the latter to another operator's receiver, in the same way as when

50 the corresponding relay 152 was energized by the described manipulation of listening key 144 of link connector A. Pilot lamp 719 being illuminated, the operator's attention is called to the energized line lamp of the calling line.

Referring now to Figure 4: This figure represents various modifications of the hereinbefore described call distributing system. It will be understood that any of the herein- 60 after described modifications may be used without using the particular combination to be described. One modification is the use of individual line relays instead of the tens and units line relays. This feature might 65 be of special use in those exchanges where

the line equipment is already installed and it is not desired to change the same. Parts that function similarly to the same parts in Figure 1 bear the same reference numerals with the addition of the exponent (').

70 Relay 143' represents the same cut-off relay as shown in Figure 1, Part 1, connected to substation 10. The removal of the substation receiver gives path for current from battery 720 through 16', 15', 18', 19', 20', 75 21', 32', 31', 30', substation apparatus, 24', 23', 22' and to ground, energizing individual line relay 721. This gives path for current from battery 720 through the right winding of relay 34', 0', 722, 723, (0') and to ground, 80 energizing relays 34', 0' and (0'). This gives path for current from battery 720 through elements 39', 37', 20' and the described path through the substation apparatus, energizing relay 39' and thereby preventing the subsequent energization of another relay such as 0' pertaining to the same 85 100 group, in the same way as described in relation to relay 39 in Fig. 1, Part 1. Relay 39' when energized closes a path for 90 battery current through lamp 724. This is in alternative form and is used instead of the audible calling signal described in relation to relay 39. The illumination of lamp 724 indicates that a line in the 100 95 group is using the signal circuit thereof.

Relay 34' functions the same as relay 34, the only difference between the two being that relay 34' has a resistance 725 in series with contact 46' thereof.

100 Line relay 721 corresponds to line No. 0000. All the individual line relays from Nos. 0000 to 0009 would be connected to contact 20' of relay 0', contacts 722 would be connected to relay 0', and contact 723 of each line relay would be connected to unit relay (0') — (1') — (2') — (3') — (4') — (5') — (6') — (7') — (8') or (9'), according to the unit of the number.

The line relays from 0010 to 0019 would 110 be connected to the corresponding contact 20' of relay 1' and the contacts 722 connected to relay 1'.

The other line relays of the hundred 115 group would be similarly connected.

Unit relays (1') to (9') and relays 1' to 9' are not shown, their connections to each other and to relays (0')—0' being exactly the same as shown and described in relation to Figure 1, Part 1.

120 The dotted lines at 726 represent the instrumentalities associated with the corresponding wires in Figure 1, Part 1, such as relays 48—218—268 and the contacts thereof. Consequently, the energization of relay 0' gives path for current from battery 720 through elements 727, 43', 44', 725, 46', 47', (upper winding of relay 48 as shown in Figure 1, Part 1, and represented by the dotted line at 726), 728, 729, 730, 731 and to 13

ground, energizing relay 48. This closes a shunt path around resistance 725 and the upper winding of relay 48 by way of the left winding of relay 34', (lower winding 5 of relay 48, represented by the dotted line at 726), relay (0000'), relay 67' and to ground, energizing relays (0000') and 67' and deenergizing relay 34'. The energization of relay (0') closed a path for current 10 from battery 720, through elements, 732, 73', (contacts 74—75 of relay 48, represented by the dotted line at 726), relay (000') and to ground, energizing relay (000').

15 The numerical signal is produced in receiver 94' in a slightly different manner from the one already described. Interrupter 81 and relays 90—84—91 and contacts 92—92 of relay 67 are all dispensed with.

20 Instead of there being one phonographic reproducer such as 97 in Figure 1, Part 1, for each number from 0 to 9, there are four reproducers 734, 735, 736, 737, for each number, so arranged around the circumference 25 of cylinder 95', of which a cross section is shown, that a given number is reproduced in each reproducer successively. Between reproducers 737—734 there is a longer space than the other spaces between the reproducers, 30 and this provides the silent interval between completed numbers. The four reproducers shown correspond to the number 0. Reproducer 734 is associated with transmitter 738, which is in circuit with battery 720 and primary winding 739. Each of the other reproducers are correspondingly associated with a transmitter and individual primary winding of an individual induction coil or repeating coil. Therefore, the energization 35 of thousand relay (0000') gives path for voice currents from ground through secondary winding 740, contacts 103'—104' and operator's repeating coil winding 741. Operator's receiver 94' is in circuit with secondary 40 winding 742 of the operator's repeating coil, consequently, the number 0 for the thousands is reproduced in said receiver. As soon as the voice record on cylinder 95' has disengaged the needle or stylus of reproducer 734 and engaged the stylus of reproducer 735, another circuit for voice currents is closed by way of contacts 123'—124' of energized hundred relay (000'), secondary 45 743 and repeating coil winding 744, consequently, another 0 for the hundreds is reproduced in receiver 94. Reproducer 736 is similarly energized, thereby giving another path for voice currents by way of battery 720, secondary 727, elements 43', 44', 50 745, 746 and repeating coil winding 747, consequently, another 0 for the tens is reproduced in receiver 94. Reproducer 737 is similarly energized, thereby giving another path for voice currents by way of battery 55 720, secondary 732, elements 733, 73', 748

and repeating coil winding 749, consequently, another 0 for the units is reproduced in receiver 94. The long space between reproducers 734—737 now furnishes the silent interval between completed numbers before the 76 sequence is repeated. It will be evident that had any other thousand or hundred relay been energized, the corresponding thousand or hundred signal would have been produced and that had any other ten relay 75 similar to 0', or unit relay similar to (0'), been energized, the corresponding ten or unit signal would have been produced.

A condenser such as 746 leads to each thousand relay and a condenser such as 748 80 leads to each hundred relay. The relay windings furnish the necessary retardation to shunt the voice currents through the condensers, or a retardation coil may be used in series with the relays.

85 The return path for the voice currents has been shown as through ground, instead of a wire such as 41, it being understood that either way may be used.

Relays corresponding to 166 and 158 are 90 not shown, it being understood they may be used with the form shown in Figure 4.

Relays 750—751—752 correspond to relays 163—182—185 and the relays below them correspond to the other signal transfer relays of the other sections. The lower contacts of these relays represent another way of switching a section in or out, there being no provision for opening the circuit through relay 67' when all the operators at a section are engaged or absent. This was purely a precautionary detail to prevent an accidental locking up of relay 67' or corresponding relay when a position was vacant or all the signal transfer relays locked up.

100 Relay 180' operates in a different manner from relay 180. Whenever relay 34' is energized there is a shunt path to ground through this relay by way of resistance 725 and contacts 46'—130' of relay 34'. However, relay 180' is not energized by the current flowing through this shunt path on account of there being a lower resistance path to ground for the current passing through resistance 725, by way of contacts 728—729 115 of relay 67' and contacts 730—731 of relay 750. When relay 67' is energized the path to ground is made to contacts 753—754 by way of contacts 755—756 and contacts 729—757 of relay 67', and as contact 757 120 engages contact 729 before disengaging the latter from contact 728, the low resistance path is not opened. However, should there be a defective contact anywhere in circuit, or the low resistance path not be closed when relay 34' is energized, then all the current flowing through resistance 725 finds path through relay 180' and the same is energized. This gives path for current through lamp 758 energizing the same and warning 130

the chief operator of a lack of operators or trouble in some of the sections. The first section that was found not receiving any calls would indicate the location of the trouble. Contact 759 of relay 180' controls the locking windings of the signal transfer relays if they are used.

Referring now to Figure 5: This represents an alternative form for the operator's repeating coil shown in Figure 4. The repeating coil windings in Figure 4 are such that they do not repeat to each other, but all repeat to secondary winding 742. In Figure 5 I have shown how four separate coils may be used, the four secondary windings being connected in multiple to operator's telephone receiver 94'. The multiplied secondaries are of sufficient resistance and impedance so that the circuit for voice currents is always shunted through the receiver, consequently, one secondary does not repeat through another secondary to the primary associated therewith.

Referring now to Figure 6: This represents a means for performing the switching operations performed by signal switching relays 166-181-184 in Figure 1, Part 2. 760 is an operator's transmitter jack, the insertion of the plug therein causes springs 761-762 to disengage their normal contacts and engage their alternate contacts, thereby performing the same function as the energization of relays 166-181-184.

Many other changes and modifications besides those described herein may be made without departing from the spirit and scope of the invention.

It will readily be understood that instead of using the described phonographic means, any other means which reproduces the human voice may be substituted therefor. For instance, a telephone, as shown and described in U. S. Patents Nos. 661,619 and 789,336, may be used for sounding the line designations of call initiating lines in the operators' receivers. On this account and in lieu of a better term, in the following claims I use the term "phonographic means" as covering any means, mechanical or electrical, for reproducing the previously recorded human voice.

In the claims the term "relay" or "relays" is frequently used to designate a device, as shown in the drawings, whose sole function is to control electrical circuits by directly operated switching means; in contradistinction to those electrical devices which perform their switching functions by means of a series of mechanical movements.

What I claim is:—

1. A telephone exchange system including telephone lines extending from substations to an exchange switchboard, substation apparatus for initiating calls, a plurality of operator's call receivers at said

switchboard, and means at said exchange operative by said substation apparatus for automatically selecting one of said call receivers and indicating only therein the individual line designation of the call initiating line.

2. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, and means whereby a call receiver can be selected by only one of a plurality of simultaneously calling lines, becoming selectable again only after having been released from said calling line.

3. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, and means whereby a call receiver can be selected by only one calling line at a time, becoming selectable again only after having been released from said calling line and after other call receivers have first been selected.

4. A telephone exchange system including telephone lines extending from substations to an exchange switchboard, substation apparatus for initiating calls, a plurality of operators' call receivers at said switchboard, means at said exchange operative by said substation apparatus for automatically and directly selecting one of said call receivers not already selected and indicating therein the individual line designation of the call initiating line, without requiring other call receivers to be first tested for a selected condition, means whereby a call receiver can be selected by only one calling line at a time, becoming selectable again only after having been released from said calling line, and means to prevent the switching from one call receiver to another for the same call once said line designation has been indicated in one of said call receivers.

5. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a

call receiver can be selected by only one calling line at a time, becoming selectable again only after having been released from said calling line, and means to select said call receivers in a regular sequence, thereby preventing a selected receiver from being again selected until after other call receivers inferior in order of precedence established by said sequence have been first selected and whereby all the calls initiated at said substations are distributed evenly amongst the operators on duty at said switchboard.

6. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a call receiver can be selected by only one calling line at a time, becoming selectable again only after having been released from said calling line, and means whereby some of said call receivers may be selected oftener than the other call receivers, said other call receivers being selected in a regular sequence, whereby the remaining calls initiated at said substations are distributed evenly amongst said other call receivers.

7. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a call receiver can be selected by only one calling line at a time, becoming selectable again only after having been released from said calling line, and manually operated switching means whereby some of said call receivers may be selected oftener than the other call receivers, said other call receivers being selected in a regular sequence, whereby the remaining calls initiated at said substations are distributed evenly among said other call receivers.

8. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, and means whereby the exchange capacity for the re-

ceipt of simultaneous calls is equal to the number of said call receivers at said switchboard, one only of said receivers being connected to one only of the simultaneously calling lines.

9. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a call receiver can be selected by only one calling line at a time, becoming selectable again only after having been released from said calling line, means whereby as many calling lines can select said call receivers at one time as there are selectable call receivers, and means to prevent one of said call receivers from being simultaneously selected by a plurality of said calling lines.

10. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a call receiver can be selected by only one calling line at a time, becoming selectable again only after having been released from said calling line, means to prevent said call receiver from being selected again until after the call initiating line has been connected to a called line, and means to prevent one of said receivers from being simultaneously selected by a plurality of said calling lines.

11. A telephone exchange system including telephone lines extending from substations to an exchange switchboard, substation apparatus for initiating calls, a plurality of operators' call receivers at said switchboard, relays at said exchange operative by said substation apparatus, signal indicating means controlled by said relays, operating circuits for said relays, means comprising said relays and circuits exclusively for selecting one of said call receivers and means comprising said signal indicating means for indicating in said selected receiver the individual line designation of the call initiating line.

12. A telephone exchange system including telephone lines extending from substations to an exchange switchboard, substation apparatus for initiating calls, a plurality of operators' call receivers at said switchboard, relays at said exchange opera-

tive by said substation apparatus, signal indicating means controlled by said relays exclusively, operating circuits for said relays, means comprising said relays and circuits 5 exclusively for selecting one of said call receivers and means comprising said signal indicating means for indicating in said selected receiver the individual line designation of the call initiating line, and relay 10 means whereby a call receiver can be selected by only one calling line at a time, becoming selectable again only after having been released from said calling line.

13. A telephone exchange system including 15 telephone lines extending from substations to an exchange switchboard, substation apparatus for initiating calls, a plurality of operators' call receivers at said switchboard, relays at said exchange operative by said 20 substation apparatus, relay means exclusively for automatically selecting one of said call receivers and indicating therein the individual line designation of the call initiating line, relay means exclusively whereby a 25 call receiver can be selected by only one calling line at a time, becoming selectable again only after having been released from said calling line, and relay means exclusively to select said call receivers in a regular 30 sequence, whereby all the calls initiated at said substations are distributed evenly amongst the operators on duty at said switchboard.

14. A telephone exchange system including 35 telephone lines extending from substations to an exchange switchboard, substation apparatus for initiating calls, a plurality of operators' call receivers at said switchboard, relay means at said exchange operative by said substation apparatus for 40 automatically selecting one of said call receivers and indicating therein the individual line designation of the call initiating line, relay means whereby a call receiver can be selected by only one calling line at a time, 45 becoming selectable again only after having been released from said calling line, and switching means whereby some of said call receivers may be selected oftener than the other call receivers, said other call receivers 50 being selected in a regular sequence, whereby the remaining calls initiated at said substations are distributed evenly amongst said other call receivers.

15. A telephone exchange system including 55 telephone lines extending from substations to an exchange switchboard, substation apparatus for initiating calls, a plurality of operators' call receivers at said switchboard, relay means at said exchange 60 operative by said substation apparatus for automatically selecting one of said call receivers and indicating therein the individual line designation of the call initiating line, relay means whereby a call receiver can be 65 selected by only one calling line at a time,

becoming selectable again only after having been released from said calling line, and manually operated switching means whereby some of said call receivers may be selected oftener than the other call receivers, said 70 other call receivers being selected in a regular sequence, whereby the remaining calls initiated at said substations are distributed evenly amongst said other call receivers.

16. A telephone exchange system including 75 telephone lines extending from substations to an exchange switchboard, substation apparatus for initiating calls, a plurality of operators' call receivers at said switchboard, line relays at said exchange 80 less in number than said substations and operative by said substation apparatus for automatically selecting one of said call receivers and indicating therein the individual line designation of the call initiating line, 85 and relay means whereby a call receiver can be selected by only one calling line at a time, becoming selectable again only after having been released from said calling line.

17. A telephone exchange system including 90 telephone lines extending from substations to an exchange switchboard, substation apparatus for initiating calls, a plurality of operators' call receivers at said switchboard, relays at said exchange less in 95 number than said substations and operative by said substation apparatus for automatically selecting one of said call receivers and indicating therein the individual line designation of the call initiating line, relay means 100 whereby a call receiver can be selected by only one calling line at a time, becoming selectable again only after having been released from said calling line, and relay means to select said call receivers in a regular 105 sequence, whereby all the calls initiated at said substations are distributed evenly amongst the operators on duty at said switchboard.

18. A telephone exchange system including 110 telephone lines extending from substations to an exchange switchboard, substation apparatus for initiating calls, a plurality of operators' call receivers at said switchboard, relays at said exchange less in number than 115 said substations and operative by said substation apparatus for automatically selecting one of said call receivers and indicating therein the individual line designation of the call initiating line, relay means whereby a 120 call receiver can be selected by only one calling line at a time, becoming selectable again only after having been released from said calling line, and switching means whereby some of said call receivers may be selected 125 oftener than the other call receivers, said other call receivers being selected in a regular sequence whereby the remaining calls initiated at said substations are distributed evenly amongst said other call receivers. 130

19. A telephone exchange system including telephone lines extending from substations to an exchange switchboard, substation apparatus for initiating calls, a plurality of 5 operators' call receivers at said switchboard, relays at said exchange less in number than said substations and operative by said substation apparatus for automatically selecting one of said call receivers and indicating 10 therein the individual line designation of the call initiating line, relay means whereby a call receiver can be selected by only one calling line at a time, becoming selectable again only after having been released from 15 said calling line, and manually operated switching means whereby some of said call receivers may be selected oftener than the other call receivers, said other call receivers being selected in a regular sequence, where- 20 by the remaining calls initiated at said substations are distributed evenly amongst said other call receivers.

20. A telephone exchange system including groups of telephone lines extending from 25 substations to an exchange switchboard, substation apparatus for initiating calls, an operator's call receiver at said switchboard and an operating circuit therefor, a signal circuit common to the lines of each group; and 30 means at said exchange, operative by said substation apparatus, whereby a call initiating line obtains exclusive control of the signal circuit of its group, connects said signal circuit to said operating circuit, and there- 35 by indicates the individual line designation of the call initiating line in said receiver.

21. A telephone exchange system including groups of telephone lines extending from substations to an exchange switchboard, sub- 40 station apparatus for initiating calls, an operator's call receiver at said switchboard and an operating circuit therefor, a signal circuit common to the lines of each group; means at said exchange, operative by said 45 substation apparatus, whereby a call initiating line obtains exclusive control of the signal circuit of its group, connects said signal circuit to said operating circuit, and there- 50 by indicates the individual line designation of the call initiating line in said receiver, and restoring means for said signal circuit, whereby said circuit becomes available for use by other call initiating lines in the same 55 group whenever it is released from the line controlling it.

22. A telephone exchange system including groups of telephone lines extending from substations to an exchange switchboard, substation apparatus for initiating calls, an 60 operator's call receiver at said switchboard, line relays for each group less in number than the number of lines in the group, a signal circuit common to the lines of each group; means at said exchange, operative 65 by said substation apparatus, whereby a call

initiating line energizes and controls two of said line relays and thereby obtains exclusive control of the signal circuit of its group and causes said circuit to indicate the individual line designation of the call initiating 70 line in said receiver, and restoring means for said relays and signal circuit, whereby said relays and circuit becomes available for use by other call initiating lines in the same group whenever they are released from the 75 line controlling them.

23. A telephone system including groups of telephone lines extending from substations to an exchange switchboard, substation apparatus for initiating calls, a plurality of 80 operators' call receivers at said switchboard, an operating circuit for each of said receivers, a signal circuit common to the lines of each group; and means at said exchange, operative by said substation apparatus, 85 whereby a call initiating line obtains exclusive control of the signal circuit of its group until released from the call initiating line, connects said signal circuit to a selected one of said operating circuits and indicates in 90 the receiver thereof the individual line designation of the call initiating line.

24. A telephone system including groups of telephone lines extending from substations to an exchange switchboard, substation 95 apparatus for initiating calls, a plurality of operators' call receivers at said switchboard, an operating circuit for each of said receivers, a signal circuit common to the lines of each group; means at said exchange, operative by said substation apparatus, 100 whereby a call initiating line obtains exclusive control of the signal circuit of its group until released from the call initiating line, connects said signal circuit to a selected one of said operating circuits and indicates in 105 the receiver thereof the individual line designation of the call initiating line, and restoring means for said signal circuit, operative upon the connection of a link connector to 110 the calling line, thereby making said signal circuit available for use by other call initiating lines in the same group.

25. A telephone system including groups of telephone lines extending from substations to an exchange switchboard, substation apparatus for initiating calls, a plurality of operators' call receivers at said switchboard, an operating circuit for each of said receivers, a signal circuit common to the lines of 115 each group; means at said exchange, operative by said substation apparatus, whereby a call initiating line obtains exclusive control of the signal circuit of its group until released from the call initiating line, connects said signal circuit to a selected one of said operating circuits and indicates in the receiver thereof the individual line designation of the call initiating line, and means for 120 preventing the connection of more than one 125 130

of said signal circuits at the same time to one of said call receivers.

26. A telephone system including groups of telephone lines extending from substations to an exchange switchboard, substation apparatus for initiating calls, a plurality of operators' call receivers at said switchboard, an operating circuit for each of said receivers, a signal circuit common to the lines of each group; means at said exchange, operative by said substation apparatus, whereby a call initiating line obtains exclusive control of the signal circuit of its group until released from the call initiating line, connects said signal circuit to a selected one of said operating circuits and indicates in the receiver thereof the individual line designation of the call initiating line, and means for selecting said call receivers by said signal circuits in a regular sequence, whereby the initiated calls are evenly apportioned amongst the operators on duty at said switchboard.

27. A telephone system including groups of telephone lines extending from substations to an exchange switchboard, substation apparatus for initiating calls, a plurality of operators' call receivers at said switchboard, a signal circuit common to the lines of each group; means at said exchange, operative by said substation apparatus, whereby a call initiating line obtains exclusive control of the signal circuit of its group until released from the call initiating line, and causes said circuit to select one of said call receivers and indicate therein the individual line designation of the call initiating line, means for preventing the connection of more than one of said signal circuits at the same time to one of said call receivers, and switching means whereby some of said call receivers may be selected oftener than the other call receivers, said other call receivers being selected in a regular sequence, whereby the remaining calls initiated at said substations are distributed evenly amongst said other call receivers.

28. A telephone system including groups of telephone lines extending from substations to an exchange switchboard, substation apparatus for initiating calls, a plurality of operators' call receivers at said switchboard, a signal circuit common to the lines of each group; means at said exchange, operative by said substation apparatus, whereby a call initiating line obtains exclusive control of the signal circuit of its group until released from the call initiating line, and causes said circuit to select one of said call receivers and indicate therein the individual line designation of the call initiating line, means for preventing the connection of more than one of said signal circuits at the same time to one of said call receivers, and manually operated switching means whereby some of said

call receivers may be selected oftener than the other call receivers, said other call receivers being selected in a regular sequence, whereby the remaining calls initiated at said substations are distributed evenly amongst said other call receivers.

29. A telephone system including groups of telephone lines extending from substations to an exchange switchboard, substation apparatus for initiating calls, link connectors for connecting said substations, a plurality of operators' call receivers at said switchboard, line relays for each group less in number than the number of lines in the group, a signal circuit common to the lines of each group; means at said exchange, operative by said substation apparatus, whereby a call initiating line energizes two of said line relays and thereby obtains exclusive control of the signal circuit of its group and causes said circuit to select one of said call receivers and indicate therein the individual line designation of the call initiating line, and restoring means for said relays and signal circuit, operative upon the connection of one of said link connectors to the calling line, thereby making said relays and signal circuit available for use by other call initiating lines in the same group.

30. A telephone system including groups of telephone lines extending from substations to an exchange switchboard, substation apparatus for initiating calls, link connectors for connecting said substations, a plurality of operators' call receivers at said switchboard, line relays for each group less in number than the number of lines in the group, a signal circuit common to the lines of each group; means at said exchange, operative by said substation apparatus, whereby a call initiating line energizes two of said line relays and thereby obtains exclusive control of the signal circuit of its group and causes said circuit to select one of said call receivers and indicate therein the individual line designation of the call initiating line, restoring means for said relays and signal circuit, operative upon the connection of one of said link connectors to the calling line, thereby making said relays and signal circuit available for use by other call initiating lines in the same group, means for preventing the connection of more than one of said signal circuits at the same time to one of said call receivers, and means for selecting said call receivers by said signal circuits in a regular sequence, whereby the initiated calls are evenly apportioned amongst the operators on duty at said switchboard.

31. A telephone exchange system including telephone lines extending from substations to an exchange switchboard, substation apparatus for initiating calls, a plurality of sections for said switchboard and a plurality of operators' call receivers for

each of said sections, line signaling apparatus individual to each of said sections and controlling said plurality of receivers, and means at said exchange operative by said 5 substation apparatus for automatically selecting one of said sections and obtaining the exclusive control of said line signaling apparatus individual thereto until released from the call initiating line, and means for 10 selecting one only of said call receivers and indicating therein the individual line designation of the calling line.

32. A telephone exchange system including telephone lines extending from substations to an exchange switchboard, substation apparatus for initiating calls, a plurality of sections for said switchboard and a plurality of operators' call receivers for each of said sections, line signaling apparatus 15 individual to each of said sections and controlling said plurality of receivers, means at said exchange operative by said substation apparatus for automatically selecting one of said sections and obtaining the exclusive control of said line signaling apparatus individual thereto until released from the call initiating line, means for selecting one only of said call receivers and indicating therein the individual line designation of the calling line, means whereby the call receivers of a section are successively selected; and means, operative when all the call receivers of a section have been once selected, whereby said section is not again selected until after other sections and the call receivers thereat have first been similarly selected.

20

25

30

35

33. A telephone exchange system including telephone lines extending from substations to an exchange switchboard, substation apparatus for initiating calls, a plurality of sections for said switchboard and a plurality of operators' call receivers for each of said sections, line signaling apparatus individual to each of said sections and controlling said plurality of receivers, means 40 at said exchange operative by said substation apparatus for automatically selecting one of said sections and obtaining the exclusive control of said line signaling apparatus individual thereto until released from the call initiating line, means for selecting one only of said call receivers and indicating therein the individual line designation of the calling line, and means whereby the call receivers of a section are successively selected, thereby preventing the same call receiver from being selected again until after the other call receivers of the section have been first selected.

45

50

55

34. A telephone exchange system including telephone lines extending from substations to an exchange switchboard, substation apparatus for initiating calls, a plurality of sections for said switchboard and a plurality of operators' call receivers for 60

each of said sections, line signaling apparatus individual to each of said sections and controlling said plurality of receivers, means at said exchange operative by said substation apparatus for automatically selecting one of said sections and obtaining the exclusive control of said line signaling apparatus individual thereto until released from the call initiating line, means for selecting one only of said call receivers and indicating therein the individual line designation of the calling line, means whereby the call receivers of a section are successively selected; and means, operative when all the call receivers of a section have been once selected, whereby said section is not again selected until after other sections and the call receivers thereat have first been similarly selected.

65

70

75

80

35. A telephone exchange system including telephone lines extending from substations to an exchange switchboard, substation apparatus for initiating calls, a plurality of sections for said switchboard and a plurality of operators' call receivers for each of said sections, line signaling apparatus individual to each of said sections and controlling said plurality of receivers, means at said exchange operative by said substation apparatus for automatically selecting one of said sections and obtaining the exclusive control of said line signaling apparatus individual thereto until released from the call initiating line, means for selecting one only of said call receivers and indicating therein the individual line designation of the calling line, and means whereby the exchange capacity for the receipt of simultaneous calls is equal to the number of said sections at said switchboard.

85

90

95

100

36. A telephone exchange system including telephone lines extending from substations to an exchange switchboard, substation apparatus for initiating calls, a plurality of sections for said switchboard and a plurality of operators' call receivers for each of said sections, line signaling apparatus individual to each of said sections and controlling said plurality of receivers, means at said exchange operative by said substation apparatus for automatically selecting one of said sections and obtaining the exclusive control of said line signaling apparatus individual thereto until released from the call initiating line, means for selecting one only of said call receivers and indicating therein the individual line designation of the calling line, means to make each of said call receivers non-selectable, means to make said line signaling apparatus of a section non-selectable when all of said call receivers pertaining thereto have been rendered non-selectable, and means whereby as many calling lines can select said sections at one time

105

110

115

120

125

as there are selectable sections, each calling line obtaining exclusive control of the line signaling apparatus of a section.

37. A telephone exchange system including telephone lines extending from substations to an exchange switchboard, substation apparatus for initiating calls, a plurality of operators' positions at said switchboard, an operator's telephone connecting device and a call receiver for each of said positions; means at said exchange, operative by said substation apparatus, for automatically selecting one of said call receivers and indicating therein the line designation of the call initiating line, and means automatically operative when a position is vacated by the operator thereat and said device is removed from its operative connection for preventing the call receiver at said position from being selected by a call initiating line.

38. A telephone exchange system including telephone lines extending from substations to an exchange switchboard, substation apparatus for initiating calls, a plurality of operators' positions at said switchboard, an operator's telephone connecting device and a call receiver for each of said positions; means at said exchange, operative by said substation apparatus, for automatically selecting one of said call receivers and indicating therein the line designation of the call initiating line, and means automatically operative when a position is vacated by the operator thereat and said device is removed from its operative connection for causing the line designation of call initiating lines which would normally be indicated in the call receiver at said position to be indicated instead in the call receiver at another position.

39. A telephone exchange system including telephone lines extending from substations to an exchange switchboard, substation apparatus for initiating calls, a plurality of operators' positions at said switchboard; a group of link connectors, a call receiver and controlling means therefor, for each of said positions; a listening key for each of said link connectors, means at said exchange operative by said substation apparatus for automatically selecting one of said call receivers and indicating therein the line designation of the call initiating line, and means whereby the manipulation of one of said listening keys at a position operates said controlling means of that position and thereby renders the call receiver individual thereto non-selectable by a call initiating line; means to prevent the operation of said controlling means when said answering plug is inserted in a line jack of an idle line; and means, operative when the calling plug corresponding to the same link connector as said answering plug is inserted in a line jack, to render said call receiver selectable again by a call initiating line.

40. A telephone exchange system including telephone lines extending from substations to an exchange switchboard, substation apparatus for initiating calls, a plurality of operators' positions at said switchboard; a group of link connectors having individual listening keys, a call receiver, a relay in

multiple relation to a condenser, an induction coil and an operator's telephone receiver, for each of said positions; a source of electricity, means at said exchange operative by said substation apparatus for automatically selecting one of said call receivers and indicating therein the line designation of the call initiating line; and means whereby the manipulation of one of said listening keys at a position when the corresponding link connector is connected to a substation line, closes a circuit for voice currents which comprises said telephone receiver, secondary of said induction coil, condenser and substation apparatus of said line, and a circuit in branch relation to said circuit which comprises said telephone receiver, secondary, relay and source, whereby said relay is energized, thereby rendering the call receiver at the position where the listening key was manipulated non-selectable by a call initiating line until said key is restored to its normal position.

41. A telephone exchange system including telephone lines extending from substations to an exchange switchboard, substation apparatus for initiating calls, a plurality of operators' positions at said switchboard; a group of link connectors, a call receiver and controlling means therefor, for each of said positions; an answering plug and a calling plug for each of said link connectors, means at said exchange operative by said substation apparatus for automatically selecting one of said call receivers and indicating therein the line designation of the call initiating line, means whereby the insertion of one of said answering plugs at a position in a line jack of a calling line operates said controlling means of that position and thereby renders the call receiver individual thereto non-selectable by a call initiating line; means to prevent the operation of said controlling means when said answering plug is inserted in a line jack of an idle line; and means, operative when the calling plug corresponding to the same link connector as said answering plug is inserted in a line jack, to render said call receiver selectable again by a call initiating line.

42. A telephone exchange system including telephone lines extending from substations to an exchange switchboard, substation apparatus for initiating calls, a plurality of operators' positions at said switchboard; a group of link connectors, a call receiver and controlling means therefor, for each of said positions; an answering plug and a calling plug for each of said link connectors, means at said exchange operative by said substation apparatus for automatically selecting one of said call receivers not already selected and indicating therein the line designation of the call initiating line,

without requiring other call receivers to be first tested for a selected condition, means whereby the insertion of one of said answering plugs at a position in a line jack of a calling line operates said controlling means of that position and thereby renders the call receiver individual thereto non-selectable by a call initiating line; means to prevent the operation of said controlling means when 5 said answering plug is inserted in a line jack of an idle line; means, operative when the calling plug corresponding to the same link connector as said answering plug is inserted in a line jack, to render said call 10 receiver selectable again by a call initiating line.

43. A telephone exchange system including telephone lines extending from substations to an exchange switchboard, substation 20 apparatus for initiating calls, a plurality of operators' positions at said switchboard; a group of link connectors, a call receiver and controlling means therefor, for each of said positions; an answering plug and a calling 25 plug for each of said link connectors, means at said exchange operative by said substation apparatus for automatically selecting one of said call receivers and indicating therein the line designation of the call initiating line, means whereby the insertion 30 of one of said answering plugs at a position in a line jack of a calling line operates said controlling means of that position and thereby renders the call receiver individual thereto non-selectable by a call initiating line; means, operative when the calling plug corresponding to the same link connector as said answering plug is inserted in a line jack, to render said call receiver selectable 35 again by a call initiating line, and means to prevent the operation of said controlling means should said answering plug be inserted in a line jack of a line other than a line which is actually initiating a call.

45. 44. A telephone exchange system including telephone lines extending from substations to an exchange switchboard, substation apparatus for initiating calls, a plurality of operators' positions at said switchboard; a group of link connectors having individual answering and calling plugs, a call receiver, a relay in multiple relation to a condenser, an induction coil and an operator's telephone receiver, for each of said positions; a source of electricity, means at said exchange operative by said substation apparatus for automatically selecting one of said call receivers and indicating therein the line designation of the call initiating 50 line, whereby the insertion of one of said answering plugs in a line jack of a calling line closes a circuit for voice currents which comprises said telephone receiver, secondary of said induction coil, condenser and substation apparatus of said line, and a circuit in 55 60 65

branch relation to said circuit which comprises said telephone receiver, secondary, relay and source, whereby said relay is energized, thereby rendering the call receiver at the position where said answering plug was 70 inserted in said jack non-selectable by a call initiating line, and means to de-energize said relay when the calling plug of the same link connector to which said answering plug pertains is inserted in a line jack, thereby 75 rendering said call receiver selectable again by a call initiating line.

45. A telephone exchange system including telephone lines extending from substations to an exchange switchboard, substation apparatus for initiating calls, a plurality of operators' call receivers at said switchboard, a warning signal at said exchange, means at said exchange, operative by said substation apparatus for 80 automatically selecting one of said call receivers and indicating therein the line designation of the call initiating line, means whereby a call receiver can be selected by only one call initiating line at a time, means 85 operative when there is no call receiver selectable, whereby a line initiating a call operates said warning signal, and means operative as soon as there is a call receiver selectable for discontinuing said signal. 90

46. A telephone exchange system including telephone lines extending from substations to an exchange switchboard, substation apparatus for initiating calls, a plurality of operators' call receivers at said 100 switchboard, a registering device, means at said exchange operative by said substation apparatus for automatically selecting one of said call receivers and indicating therein the line designation of the call initiating line, 105 means whereby a call receiver can be selected by only one call initiating line at a time, and means operative when there is no call receiver selectable, whereby a line initiating a call operates said registering device. 110

47. A telephone exchange system including telephone lines extending from substations to an exchange switchboard, substation apparatus for initiating calls, link connectors for connecting said substations, a plurality of operators' call receivers at said switchboard, means at said exchange operative by said substation apparatus for automatically selecting one of said call receivers 115 and indicating therein the line designation of the call initiating line, and means under the control of said apparatus when connected by said link connectors for signaling the connecting operator and also at the same 120 time for preventing said operator's call receiver from being selected by a calling line while said signaling continues.

48. A telephone exchange system including telephone lines extending from substa- 130

tions to an exchange switchboard, substation apparatus for initiating calls, link connectors for connecting said substations, a plurality of operators' call receivers at said 5 switchboard, means at said exchange operative by said substation apparatus for automatically selecting one of said call receivers and indicating therein the line designation of the call initiating line, means under the 10 control of said apparatus when connected by said link connectors for signaling the connecting operator and also at the same time for preventing said operator's call receiver from being selected by a calling line while 15 said signaling continues, and means to prevent a substation from being telephonically connected to more than one of said link connectors at one time.

49. A telephone exchange system including 20 telephone lines extending from substations to an exchange switchboard, substation apparatus for initiating calls, link connectors for connecting said substations, a plurality of operators' call receivers at said 25 switchboard, means at said exchange operative by said substation apparatus for automatically selecting one of said call receivers and indicating therein the line designation of the call initiating line, and means, 30 under the control of said apparatus at one substation independent of the other connected substation when connected by said link connectors, for signaling the connecting operator and also at the same time for preventing 35 said operator's call receiver from being selected by a calling line while said signaling continues.

50. A telephone exchange system including 40 telephone lines extending from substations to an exchange switchboard, substation apparatus for initiating calls, link connectors for connecting said substations, two relays for each of said link connectors, a plurality of operators' call receivers at said 45 switchboard, means at said exchange operative by said substation apparatus for automatically selecting one of said call receivers and indicating therein the line designation of the call initiating line; and means, under 50 the control of said apparatus at one substation independent of the other connected substation when connected by said link connectors, for energizing one or both of said relays and thereby signaling the connecting operator and also at the same time preventing 55 said operator's call receiver from being selected by a calling line while said signaling continues.

51. A telephone exchange system including 60 telephone lines extending from substations to an exchange switchboard, substation apparatus for initiating calls, a plurality of operators' positions at said switchboard, a group of link connectors having in- 65 dividual disconnect signals and a call re-

ceiver for each of said positions, means at said exchange operative by said substation apparatus for automatically selecting one of said call receivers and indicating therein the line designation of the call initiating line, 70 and means under the control of apparatus at said substations when connected to said link connectors for energizing the corresponding disconnect signal and also at the same time for preventing the call receiver of the corresponding position from being selected by a call initiating line during the time said signal remains energized. 75

52. A telephone exchange system including 80 telephone lines extending from substations to an exchange switchboard, substation apparatus for initiating calls, a plurality of operators' positions at said switchboard, a group of link connectors having individual recall signals and a call receiver 85 for each of said positions, means at said exchange operative by said substation apparatus for automatically selecting one of said call receivers and indicating therein the line designation of the call initiating line, and means under the control of apparatus at 90 said substations when connected to said link connectors for energizing the corresponding recall signal and also at the same time for preventing the call receiver of the corresponding position from being selected by a call initiating line during the time said signal remains energized. 95

53. A telephone exchange system including 100 telephone lines extending from substations to an exchange switchboard, substation apparatus for initiating calls, a plurality of operators' positions at said switchboard; a group of link connectors having individual calling and called line visual recall signals, 105 and a call receiver for each of said positions; means at said exchange operative by said substation apparatus for automatically selecting one of said call receivers and indicating therein the line designation of the 110 call initiating line, and means under the control of apparatus at a substation of a calling or called line when connected by said link connectors for energizing said recall signal corresponding to its line, and also at the 115 same time for preventing the call receiver of the corresponding position from being selected by a call initiating line during the time said signal remains energized, whereby either of said connected substations has independent control of its own recall signal and can prevent the connecting operator from being signaled by a calling line as long as said signal remains energized. 120

54. A telephone exchange system including 125 telephone lines extending from substations to an exchange switchboard, substation apparatus for initiating calls, link connectors for connecting said substations, a busy test system associated with each of said 130

link connectors, a plurality of operators' call receivers at said switchboard, means at said exchange operative by said substation apparatus for automatically selecting one of said 5 call receivers and indicating therein the line designation of the call initiating line, means under the control of said apparatus when connected by said link connectors for signaling the connecting operator and also at 10 the same time for preventing said operator's call receiver from being selected by a calling line while said signaling continues, and means whereby a busy test made on a line which is signaling the connecting operator 15 will produce a different busy signal from that produced when the tested line is busy but is not signaling.

55. A telephone exchange system including telephone lines extending from substations to an exchange switchboard, substation apparatus for initiating calls, link connectors for connecting said substations, a busy test system associated with each of said link connectors, a plurality of operators' call receivers at said switchboard, means at said exchange operative by said substation apparatus for automatically selecting one of said call receivers and indicating therein the line designation of the call initiating line; means, 20 under the control of said apparatus at one substation independent of the other connected substation when connected by said link connectors, for signaling the connecting operator and also at the same time for preventing said operator's call receiver from being selected by a calling line while said signaling continues; and means whereby a busy test made on a line which is signaling the connecting operator will produce a different busy signal from that produced when the tested line is busy but is not signaling.

56. A telephone exchange system including telephone lines extending from substations to an exchange switchboard, substation apparatus for initiating calls, a plurality of operators' positions at said switchboard, a group of link connectors having individual disconnect and recall signals, a call receiver for each of said positions, means at said exchange operative by said substation apparatus for automatically selecting one of said call receivers and indicating therein the line designation of the call initiating line, means under the control of apparatus at said substations when connected to said link connectors for energizing the corresponding disconnect or recall signal, and means operative when either of said signals is operated for preventing the call receiver of the corresponding position from being selected by a call initiating line during the time said signal remains energized.

57. A telephone exchange system including telephone lines extending from substations to an exchange switchboard, substation

apparatus for initiating calls, a plurality of operators' positions at said switchboard, a group of link connectors having individual calling line disconnect and recall signals and separate called-for line disconnect and recall signals, a call receiver for each of said positions, means at said exchange operative by said substation apparatus for automatically selecting one of said call receivers and indicating therein the line designation of the call initiating line, means under the control of apparatus at the substations of the calling and called-for line when connected by said link connectors and operative when said substation apparatus of one substation is in a different operative condition from that of the other for energizing either of said signals pertaining to its line without energizing either of the signals of the other line, and means operative when any of said signals are operated for preventing the call receiver of the corresponding position from being selected by a call initiating line during the time any of said signals remain energized.

58. A telephone exchange system including telephone lines extending from substations to an exchange, substation apparatus for signaling an exchange operator having a normal and abnormal condition for said apparatus, link connectors for connecting said lines, a separate visual ringing signal instrumentality for each of said link connectors; automatic means, operative when said link connector is connected to a called line, to energize said instrumentality as long as said apparatus at a substation of said line remains in its normal condition; automatic means, operative when said apparatus is changed to its abnormal condition, to deenergize said instrumentality; and automatic means, operative when said apparatus is subsequently restored to its normal condition, to prevent the re-energization of said instrumentality during the time said link connector remains connected to said line.

59. A telephone exchange system including telephone lines extending from substations to an exchange, substation apparatus for signaling an exchange operator having a normal and abnormal condition for said apparatus, a link connector for connecting said lines, a visual ringing signal for said link connector; means, operative when said link connector is connected to a called line, to energize said signal as long as said apparatus at a substation of said line remains in its normal condition; means, operative when said apparatus is changed to its abnormal condition, to deenergize said signal; means, operative when said apparatus is subsequently restored to its normal condition, to prevent the re-energization of said signal during the time said link connector remains connected to said line, means to

prevent the energization of said signal when said link connector is connected to a busy line, and means to subsequently energize said signal when said busy line becomes 5 idle.

60. A telephone exchange system including telephone lines extending from substations to an exchange, substation apparatus for signaling an exchange operator having 10 a normal and abnormal condition for said apparatus, a link connector for connecting said lines, a separate visual ringing signal instrumentality for said link connector; means, operative when a calling line is connected to a called line by way of said link connector, to energize said signal instrumentality as long as said apparatus at a 15 substation of said called line remains in its normal condition and said apparatus at a 20 substation of said calling line remains in its abnormal condition; means, operative when either said apparatus at the called line substation is changed to its abnormal condition or said apparatus at the calling line 25 substation is changed to its normal condition, whereby said signal instrumentality is de-energized; and means, operative when the condition of either of said apparatus is changed again, to prevent the re-energization 30 of said signal instrumentality during the time said link connector remains connected to said lines.

61. A telephone exchange system including telephone lines extending from substations to an exchange, substation apparatus for signaling an exchange operator having a normal and abnormal condition for said apparatus, a link connector for connecting said lines, a ring-back signal instrumentality 35 individual to said link connector; means, operative during the time said link connector remains connected to a calling line, to energize said signal instrumentality as long as said apparatus at a substation of said 40 line remains in its normal condition; means, operative when said apparatus is changed to its abnormal condition, to de-energize said signal instrumentality; and means operative when said apparatus is subsequently re- 45 stored to its normal condition, to prevent the re-energization of said signal instrumentality during the time said link connector remains connected to said line.

62. A telephone exchange system including telephone lines extending from substations to an exchange, substation apparatus for signaling an exchange operator having a normal and abnormal condition for said apparatus, a link connector for connecting 50 said lines, a ring-back signal for said link connector; means, operative during the time said link connector remains connected to a calling line, to energize said signal as long as said apparatus at a substation of said 55 line remains in its normal condition; means,

operative when said apparatus is changed to its abnormal condition, to de-energize said signal; means, operative when said apparatus is subsequently restored to its normal condition, to prevent the re-energization of said signal during the time said link connector remains connected to said line, means to prevent the energization of said signal when said calling line is busy, and means to subsequently automatically energize said signal when said busy line becomes idle. 70

63. A telephone exchange system including telephone lines extending from substations to an exchange, substation apparatus 80 for signaling an exchange operator having a normal and abnormal condition for said apparatus, a link connector for connecting said lines, a ring-back signal instrumentality individual to said link connector; means, operative when a calling line is connected to a called line by way of said link connector, to energize said signal instrumentality as long as said apparatus at a substation of said calling line remains in its normal condition 85 and said apparatus at a substation of said called line remains in its abnormal condition; means, operative when either said apparatus at the calling line substation is changed to its abnormal condition or said 90 apparatus at the called line substation is changed to its normal condition, whereby said signal instrumentality is de-energized; and means, operative when the condition of either of said apparatus is changed again, 95 to prevent the re-energization of said signal instrumentality during the time said link connector remains connected to said lines.

64. A telephone exchange system including telephone lines extending from substations to an exchange, calling signal apparatus at said substations, substation apparatus for signaling an exchange operator having a normal and abnormal condition for said apparatus, a link connector for connecting said lines, a source of signaling current; means, operative when a calling line is connected by way of said link connector to a called line, to automatically impress current from said source on the called 105 line to operate said calling signal apparatus; means for automatically impressing current from said source on the calling line for operating the calling signal apparatus of the calling substation, without disturbing said 110 link connector connection, provided said substation apparatus of the calling line has been restored to its normal condition; and means for automatically discontinuing the impression of current from said source on the calling line, when said apparatus at the formerly calling substation is changed to its abnormal condition. 115

65. A telephone exchange system including telephone lines extending from substa- 120

tions to an exchange, calling signal apparatus at said substations, substation apparatus for signaling an exchange operator having a normal and abnormal condition for 5 said apparatus, a link connector for connecting said lines, a source of signaling current; means, operative when a calling line is connected by way of said link connector to a called line, to automatically impress 10 current from said source on the called line to operate said calling signal apparatus; means for automatically impressing current from said source on the calling line for operating the calling signal apparatus of the 15 calling substation, without disturbing said link connector connection, provided said substation apparatus of the calling line has been restored to its normal condition; means for automatically discontinuing the impression 20 of current from said source on the calling line, when said apparatus at the formerly calling substation is changed to its abnormal condition, and means for discontinuing said impression, previous to said 25 change to abnormal condition of apparatus at the formerly calling substation, when said apparatus at the formerly called substation is restored to its normal condition.

66. A telephone exchange system including telephone lines extending from substations to an exchange, calling signal apparatus at said substations, substation apparatus for signaling an exchange operator having a normal and abnormal condition 30 for said apparatus, a link connector for connecting said lines, a source of signaling current; means, operative when a calling line is connected by way of said link connector to a called line, to automatically impress 35 current from said source on the called line to operate said calling signal apparatus; means for automatically impressing current from said source on the calling line for operating the calling signal apparatus of the 40 calling substation, without disturbing said link connector connection, provided said substation apparatus of the calling line has been restored to its normal condition; means for automatically discontinuing the impression 45 of current from said source on the calling line, when said apparatus at the formerly calling substation is changed to its abnormal condition, means to prevent the operation of said second mentioned means 50 when said calling line is busy, and means to subsequently automatically operate said means when said busy line becomes idle.

67. A telephone exchange system including telephone lines extending from substations to an exchange, substation apparatus for signaling an exchange operator having a normal and abnormal condition for said apparatus, a link connector for connecting said lines, a ring-back relay for said link 55 connector; means, operative during the time

said link connector remains connected to a calling line, to energize said relay as long as said apparatus at a substation of said line remains in its normal condition; means, operative when said apparatus is changed to 70 its abnormal condition, to de-energize said relay; and means, operative when said apparatus is subsequently restored to its normal condition, to prevent the re-energization of said relay during the time said link 75 connector remains connected to said line.

68. A telephone exchange system including telephone lines extending from substations to an exchange, substation apparatus for signaling an exchange operator having 80 a normal and abnormal condition for said apparatus, a link connector for connecting said lines, a ring-back relay for said link connector; means, operative when a calling line is connected to a called line by way of 85 said link connector, to energize said relay as long as said apparatus at a substation of said calling line remains in its normal condition and said apparatus at a substation of said called line remains in its abnormal condition; means operative when either said apparatus at the calling line substation is changed to its abnormal condition or said apparatus at the called line substation is changed to its normal condition, whereby said relay is de-energized; and means, operative when the condition of either of said apparatus is changed again, to prevent the re-energization of said relay 90 during the time said link connector remains 95 connected to said lines.

69. A telephone exchange system including telephone lines extending from substations to an exchange, link connectors for connecting said substations, a relay for each 105 of said link connectors, calling signal apparatus at said substations, a source of alternating and a source of direct current, an interrupter for impressing portions only of the alternations of said alternating current 110 source around said relay to a called line and for short-circuiting said line momentarily after each such impression of alternating current, thereby removing any static charge from said line, and an interrupter 115 for controlling the passage of current from said direct current source through said relay to said called line, the alternations of the alternating current as impressed on the line being of such rapidity as to continuously operate said calling signal apparatus, the direct current being connected to said line only between alternations of said alternating current as impressed on said line and after said line has been momentarily short-circuited by said first mentioned interrupter; whereby said relay is never traversed by said alternating current, nor can receive static discharges from said line, and is operated by said direct current only when 120 125 130

apparatus under the control of said called substation is substituted for said calling signal apparatus.

70. A telephone exchange system including telephone lines extending from substations to an exchange, a group of link connectors for connecting said substations, a relay having two normally disengaged contacts connected respectively to the terminals 10 of the winding of said relay, an induction coil, a telephone receiver connected in circuit with the secondary of said induction coil, a source of electricity; and means, under the control of apparatus at a substation 15 when connected to one of said link connectors, for closing a circuit comprising said source, the winding of said relay and the primary of said induction coil, thereby intermittently energizing said relay on account of said relay being short-circuited as 20 soon as said contacts thereof become engaged and re-energized again as soon as said contacts become disengaged, whereby a variable current is produced in said primary by the change of resistance in said 25 circuit due to the intermittent exclusion from said circuit of said winding and an audible signal is sounded in said receiver due to its connection to the secondary of 30 said induction coil.

71. A telephone exchange system including telephone lines extending from substations to an exchange, a group of link connectors for connecting said substations, a relay having two normally disengaged contacts connected respectively to the terminals 35 of the winding of said relay, an induction coil, a telephone receiver connected in circuit with the secondary of said induction coil, a source of electricity; means, under the control of apparatus at a substation 40 when connected to one of said link connectors, for closing a circuit comprising said source, the winding of said relay and the primary of said induction coil, thereby 45 intermittently energizing said relay on account of said relay being short-circuited as soon as said contacts thereof become engaged and re-energized again as soon as said contacts become disengaged, whereby a variable 50 current is produced in said primary due to the intermittent exclusion from said circuit of said winding and an audible signal is sounded in said receiver due to its connection to the secondary of said induction coil; and means, also under the control of said apparatus when connected to one of said link connectors, for increasing the variations in said variable current and consequently increasing the strength of said audible signal.

72. A telephone exchange system including telephone lines extending from substations to an exchange, a group of link connectors for connecting said substations, a 65 relay having two normally disengaged con-

tacts connected respectively to the terminals of the winding of said relay, a relay having two normally engaged contacts connected respectively so as to short-circuit a part of said winding, an induction coil, a 70 telephone receiver connected in circuit with the secondary of said induction coil, a source of electricity; means, under the control of apparatus at a substation when connected to one of said link connectors, for closing a 75 circuit comprising said source, the winding of said first mentioned relay and the primary of said induction coil, thereby intermittently energizing said first mentioned relay on account of said relay being short-circuited as soon as said contacts thereof become engaged and re-energized again as soon as said contacts become disengaged, whereby a variable current is produced in said primary due to the intermittent exclusion 80 from said circuit of said winding and an audible signal is sounded in said receiver due to its connection to the secondary of said induction coil; and means, also under the control of said apparatus when connected to one of said link connectors, to also energize said second mentioned relay, thereby increasing the resistance of said winding by removing said short-circuit from around a part of said winding, thereby increasing 85 the variations in said variable current and thereby increasing the strength of said audible signal.

73. A telephone exchange system including telephone lines extending from substations to an exchange switchboard, substation apparatus for initiating calls, a plurality of operators' call receivers at said switchboard, means operative when a substation initiates a call for automatically selecting one of 100 said call receivers and indicating therein the individual line designation of the call initiating line and to sound an audible tone signal in the telephone receiver at said calling substation, providing said substation's 105 line wires and call distributing means at the exchange are in operating condition, and means under the control of an operator to discontinue said audible signal, indicating that said operator is ready to receive a communication from said substation.

74. A telephone exchange system including telephone lines extending from substations to an exchange, call distributing means at said exchange, substation means 120 for initiating calls, means operative when a substation initiates a call to sound an audible signal in the telephone receiver at said calling substation, providing said substation's line wires and call distributing 125 means at the exchange are in operating condition, means under the control of an operator to discontinue said audible signal, indicating that said operator is ready to receive a communication from said substa- 130

tion, said means operative when a substation initiates a call comprising a plurality of relays at said exchange, a source of variable current and a substation induction coil, an operating circuit connecting said relays and source to the primary of said induction coil, whereby said audible signal is sounded in said receiver on account of its connection to the secondary of said induction coil; and 10 said means under the control of an operator comprises a cut-off relay and a link connector, whereby the connection of said link connector to the call initiating line energizes said cut-off relay and thereby disconnects said induction coil from said operating circuit.

75. A telephone exchange system including telephone lines extending from substations to an exchange switchboard, substation apparatus for initiating calls, a plurality of telephone receivers at said switchboard, means at said exchange comprising phonographic means common to a plurality of lines and operative by said substation apparatus for automatically selecting one of said receivers and sounding only therein the line designation of the call initiating line, and means whereby one of said receivers can be selected by only one calling line at a time, becoming selectable again only after having been released from said calling line.

76. A telephone exchange system including telephone lines extending from substations to an exchange switchboard, substation apparatus for initiating calls, a plurality of telephone receivers at said switchboard, means at said exchange comprising phonographic means common to a plurality of lines and operative by said substation apparatus for automatically selecting one of said receivers and sounding therein the line designation of the call initiating line, means whereby one of said receivers can be selected 45 by only one calling line at a time, becoming selectable again only after having been released from said calling line, and means to select said receivers in a regular sequence, whereby a selected receiver is not again selected until after other receivers have 50 first been selected and all the calls initiated at said substations are distributed evenly amongst the operators on duty at said switchboard.

55. 77. A telephone exchange system including telephone lines extending from substations to an exchange switchboard, substation apparatus for initiating calls, a plurality of telephone receivers at said switchboard, means at said exchange operative by said substation apparatus for automatically selecting one of said receivers, phonographic means common to a plurality of lines for reproducing in said receiver only words representing the line designation of the call ini-

tiating line, and means whereby one of said receivers can only be selected by one call initiating line at a time, becoming selectable again only after having been released from said line and after other call receivers have 70 first been selected.

78. A telephone exchange system including telephone lines extending from substations to an exchange switchboard, substation apparatus for initiating calls, a plurality of telephone receivers at said switchboard, means at said exchange operative by said substation apparatus for automatically selecting one of said receivers, phonographic means for reproducing in said receiver words representing the line designation of the call initiating line, means whereby one of said receivers can only be selected by one call initiating line at a time, becoming selectable again only after having been released from said line, and means to select said receivers in a regular sequence, thereby preventing a selected receiver from being again selected until after other call receivers inferior in order of precedence 85 established by said sequence have been first selected and whereby all the calls initiated at said substations are distributed evenly amongst the operators on duty at said switchboard.

90 79. A telephone exchange system including telephone lines extending from substations to an exchange switchboard, substation apparatus for initiating calls, a plurality of telephone receivers at said switchboard, means at said exchange operative by said substation apparatus for automatically selecting one of said receivers, phonographic means for reproducing in said receiver words representing the line designation of the call initiating line, means whereby one of said receivers can only be selected by one call initiating line at a time, becoming selectable again only after having been released from said line, and switching 95 means whereby some of said receivers may be selected oftener than the other receivers, said other receivers being selected in a regular sequence, whereby the remaining calls initiated at said substations are distributed 100 evenly amongst said other receivers.

80. A telephone exchange system including telephone lines extending from substations to an exchange switchboard, substation apparatus for initiating calls, a plurality of telephone receivers at said switchboard, means at said exchange operative by said substation apparatus for automatically selecting one of said receivers, phonographic means for reproducing in said receiver words representing the line designation of the call initiating line, means whereby one of said receivers can only be selected by one call initiating line at a time, becoming selectable again only after having been 105 110 115 120 125 130

- released from said line, and manually operated switching means whereby some of said receivers may be selected oftener than the other receivers, said other receivers being selected in a regular sequence, whereby the remaining calls initiated at said substations are distributed evenly amongst said other receivers. 5
81. A telephone exchange system including telephone lines extending from substations to an exchange switchboard, substation apparatus for initiating calls, a plurality of telephone receivers at said switchboard, means at said exchange comprising phonographic means common to a plurality of lines and operative by said substation apparatus for automatically selecting one of said receivers and sounding therein the line designation of the call initiating line, means whereby one of said receivers can be selected by only one of a plurality of simultaneously calling lines, becoming selectable again only after having been released from said calling line, and means to prevent said receiver from being selected again until after the call initiating line has been connected to a called line. 10
82. A telephone exchange system including groups of telephone lines extending from substations to an exchange switchboard, substation apparatus for initiating calls, an operator's telephone receiver at said switchboard, a signal circuit common to the lines of each group; means at said exchange, operative by said substation apparatus, whereby a call initiating line obtains exclusive control of the signal circuit of its group, phonographic means common to said groups and controlled by said circuit to reproduce words indicating the individual line designation of the call initiating line in said receiver, and restoring means for said signal circuit, whereby said circuit becomes available for use by other call initiating lines in the same group whenever it is released from the line controlling it. 15
83. A telephone exchange system including groups of telephone lines extending from substations to an exchange switchboard, substation apparatus for initiating calls, an operator's telephone receiver at said switchboard, line relays for each group less in number than the number of lines in the group, a signal circuit common to the lines of each group; means at said exchange, operative by said substation apparatus; whereby a call initiating line energizes two of said line relays and thereby obtains exclusive control of the signal circuit of its group, phonographic means controlled by said circuit to reproduce words indicating the individual line designation of the call initiating line in said receiver, and restoring means for said signal circuit, whereby 20
- said circuit becomes available for use by other call initiating lines in the same group whenever it is released from the line controlling it. 25
84. A telephone exchange system including groups of telephone lines extending from substations to an exchange switchboard, substation apparatus for initiating calls, link connectors for connecting said substations, a plurality of operators' telephone receivers at said switchboard, a signal circuit common to the lines of each group; means at said exchange, operative by said substation apparatus whereby a call initiating line obtains exclusive control of the signal circuit of its group and causes said circuit to select one of said call receivers, phonographic means common to said groups for reproducing therein words indicating the individual line designation of the call initiating line, restoring means for said signal circuit, operative upon the connection of one of said link connectors to the calling line, thereby making said signal circuit available for use by other call initiating lines in the same group, and means for preventing the connection of more than one of said signal circuits at the same time to one of said receivers. 30
85. A telephone exchange system including groups of telephone lines extending from substations to an exchange switchboard, substation apparatus for initiating calls, link connectors for connecting said substations, a plurality of operators' telephone receivers at said switchboard, a signal circuit common to the lines of each group; means at said exchange, operative by said substation apparatus whereby a call initiating line obtains exclusive control of the signal circuit of its group and causes said circuit to select one of said call receivers, phonographic means common to said groups for reproducing therein words indicating the individual line designation of the call initiating line, restoring means for said signal circuit, operative upon the connection of one of said link connectors to the calling line, thereby making said signal circuit available for use by other call initiating lines in the same group, means for preventing the connection of more than one of said signal circuits at the same time to one of said receivers, and means for selecting said receivers by said signal circuits in a regular sequence, whereby the initiated calls are evenly apportioned amongst the operators on duty at said switchboard. 35
86. A telephone exchange system including groups of telephone lines extending from substations to an exchange switchboard, substation apparatus for initiating calls, link connectors for connecting said substations, a plurality of operators' telephone receivers at said switchboard, line relays for each 40

group less in number than the number of lines in the group, a signal circuit common to the lines of each group; means at said exchange, operative by said substation apparatus, whereby a call initiating line energizes two of said line relays and thereby obtains exclusive control of the signal circuit of its group and causes said circuit to select one of said call receivers, phonographic means for reproducing therein words indicating the individual line designation of the call initiating line, restoring means for said relays and signal circuit, operative upon the connection of one of said link connectors to the calling line, thereby making said relays and signal circuit available for use by other call initiating lines in the same group, and means for preventing the connection of more than one of said signal circuits at the same time to one of said receivers.

87. A telephone exchange system including groups of telephone lines extending from substations to an exchange switchboard, substation apparatus for initiating calls, link connectors for connecting said substation, a plurality of operators' telephone receivers at said switchboard, line relays for each group less in number than the number of lines in the group, a signal circuit common to the lines of each group; means at said exchange, operative by said substation apparatus, whereby a call initiating line energizes two of said line relays and thereby obtains exclusive control of the signal circuit of its group and causes said circuit to select one of said call receivers, phonographic means for reproducing therein words indicating the individual line designation of the call initiating line, restoring means for said relays and signal circuit, operative upon the connection of one of said link connectors to the calling line, thereby making said relays and signal circuit available for use by other call initiating lines in the same group, means for preventing the connection of more than one of said signal circuits at the same time to one of said receivers, and means for selecting said receivers by said signal circuits in a regular sequence, whereby the initiated calls are evenly apportioned amongst the operators on duty at said switchboard.

88. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus individual to each of said sections and controlling said receivers thereat, means at said exchange operative by said substation apparatus for automatically selecting one of said

sections and obtaining the exclusive control of said line signaling apparatus individual thereto until released from the call initiating line, and for selecting one only of said receivers and sounding therein the individual line designation of the calling line, means to make each of said receivers non-selectable, and means to make said line signaling apparatus of a section non-selectable when all of said receivers pertaining thereto have been rendered non-selectable.

89. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus individual to each of said sections and controlling said receivers thereat, means at said exchange operative by said substation apparatus for automatically selecting one of said sections and obtaining the exclusive control of said line signaling apparatus individual thereto until released from the call initiating line, and for selecting one only of said receivers and sounding therein the individual line designation of the calling line, and means whereby said receivers of a section are successively selected, thereby preventing the same receiver from being selected again until after the other receivers of the section have been first selected.

90. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus individual to each of said sections and controlling said receivers thereat, means at said exchange operative by said substation apparatus for automatically selecting one of said sections and obtaining the exclusive control of said line signaling apparatus individual thereto until released from the call initiating line, and for selecting one only of said receivers and sounding therein the individual line designation of the calling line, and means operative when all of said receivers of a section have been once selected, whereby said section is not again selected until after other sections and said receivers thereat have first been similarly selected.

91. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus individual

to each of said sections and controlling said receivers thereat, means at said exchange operative by said substation apparatus for automatically selecting one of said sections 5 and obtaining the exclusive control of said line signaling apparatus individual thereto until released from the call initiating line, and for selecting one only of said receivers, phonographic means for reproducing in said 10 receiver words indicating the individual line designation of the calling line, means to make each of said receivers non-selectable, and means to make said line signaling apparatus of a section non-selectable when all 15 of said receivers pertaining thereto have been rendered non-selectable.

92. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus 20 individual to each of said sections and controlling said receiver thereat, means at said exchange operative by said substation apparatus for automatically selecting one of said sections and obtaining the exclusive 25 control of said line signaling apparatus individual thereto until released from the call initiating line, and for selecting one only of said receivers, phonographic means for reproducing in said receiver words indicating 30 the individual line designation of the calling line, and means whereby said receivers of a section are successively selected, thereby preventing the same receiver from being selected again until after the other receivers 35 of the section have been first selected.

93. A telephone exchange system including telephone lines extending from substations to an exchange switchboard, substation apparatus for initiating calls, a plurality of sections for said switchboard and a plurality of operators' positions for each of said sections, a telephone receiver for each of said positions, line signaling apparatus individual to each of said sections and controlling 45 said receivers thereat, means at said exchange operative by said substation apparatus for automatically selecting one of said sections and obtaining the exclusive control of said line signaling apparatus individual thereto 50 until released from the call initiating line, and for selecting one only of said receivers, phonographic means for reproducing in said receiver words indicating the individual line designation of the calling line, and means 55 operative when all of said receivers of a section have been once selected, whereby said section is not again selected until after other sections and said receivers thereat have first been similarly selected.

65 94. A telephone exchange system includ-

ing telephone lines extending from substations to an exchange switchboard, substation apparatus for initiating calls, a plurality of operators' call receivers at said switchboard; section selecting, battery control, section 70 connecting, thousand signal and hundred signal relays at said exchange operative by said substation apparatus; a calling signal indicating means controlled by the operation of said relays, operating circuits connecting 75 said relays; means comprising said relays and circuits for selecting one of said call receivers and means for indicating in said selected receiver the individual line designation of the call initiating line. 80

95. A telephone exchange system including telephone lines extending from substations to an exchange switchboard, substation apparatus for initiating calls, a plurality of operators' call receivers at said 85 switchboard; section selecting, battery control, section connecting, thousand signal, hundred signal, call transfer, battery cut-off and signal controlling relays at said exchange operative by said substation apparatus; a calling signal indicating means controlled by the operation of said relays, operating circuits connecting said relays; means comprising said relays and circuits 90 for selecting one of said call receivers, means for indicating in said selected receiver the individual line designation of the call initiating line and means comprising said section connecting and call transfer relays, whereby a call receiver can be selected by 100 only one calling line at a time, becoming selectable again only after having been released from said calling line.

96. A telephone exchange system including telephone lines extending from substations to an exchange switchboard, substation apparatus for initiating calls, a plurality of operators' call receivers at said switchboard; section selecting, battery control, section connecting, thousand signal, hundred signal, call transfer, battery cut-off, signal controlling, position lock-out, position controlling and position signal transfer relays at said exchange operative by said substation apparatus; a calling signal indicating 105 means controlled by the operation of said relays, operating circuits connecting said relays; means comprising said relays and circuits for selecting one of said call receivers and means for indicating in said selected 110 receiver the individual line designation of the call initiating line.

97. A telephone exchange system including telephone lines extending from substations to an exchange switchboard, substation apparatus for initiating calls, a plurality of operators' call receivers at said 115 switchboard; section selecting, battery control, section connecting, thousand signal, hundred signal, position controlling, posi- 120

tion lockout and position signal transfer relays at said exchange operative by said substation apparatus; a calling signal indicating means controlled, exclusively by 5 one or more of said relays, operating circuits connecting said relays, means comprising said relays and circuits exclusively for selecting one of said call receivers, means for indicating in said selected receiver the 10 individual line designation of the call initiating line and means comprising said position controlling, position lock-out and position signal transfer relays to select said call receivers in a regular sequence, whereby 15 all the calls initiated at said substations are distributed evenly amongst the operators on duty at said switchboard.

98. A telephone exchange system including telephone lines extending from substations to an exchange switchboard, substation apparatus for initiating calls, a plurality of operators' positions at said switchboard; a group of link connectors having individual listening keys, a relay in multiple relation to a condenser, an induction call and a telephone receiver for each of said positions; a source of electricity, means at said exchange operative by said substation apparatus for automatically selecting 20 one of said receivers and sounding therein the line designation of the call initiating line; and means whereby the manipulation of one of said listening keys at a position when the corresponding link connector is connected to a substation line, closes a circuit for voice currents which comprises said receiver, secondary of said induction coil, condenser and substation apparatus of said line, and a circuit in branch 25 relation to said circuit which comprises said receiver, secondary, relay and source, whereby said relay is energized, thereby rendering said receiver at the position where the listening key was manipulated non-selectable by a call initiating line.

99. A telephone exchange system including telephone lines extending from substations to an exchange switchboard, substation apparatus for initiating calls, a plurality of operators' positions at said switchboard; a group of link connectors, a telephone receiver and controlling means therefor, for each of said positions; an answering plug and a calling plug for each of said link connectors, means at said exchange comprising phonographic means and operative by said substation apparatus for automatically selecting one of said receivers and sounding therein the line designation of 50 the call initiating line, means whereby the insertion of one of said answering plugs at a position in a line jack of a calling line operates said controlling means of that position and thereby renders the receiver individual thereto non-selectable by a call initiating 55 line; means to prevent the operation of said controlling means when said answering plug is inserted in a line jack of an idle line; and means, operative when the calling plug corresponding to the same link connector as 70 said answering plug is inserted in a line jack, to render said receiver selectable again by a call initiating line.

100. A telephone exchange system including telephone lines extending from substations to an exchange switchboard, substation apparatus for initiating calls, a plurality of operators' positions at said switchboard; a group of link connectors, a telephone receiver and controlling means therefor including a relay, for each of said positions; a relay, an answering plug and a calling plug for each of said link connectors, means at said exchange operative by said substation apparatus for automatically 80 selecting one of said receivers and sounding therein the line designation of the call initiating line, means whereby the insertion of one of said answering plugs at a position in a line jack of a calling line operates said first mentioned relay and thereby operates said controlling means of that position and renders the receiver individual thereto non-selectable by a call initiating line, means operative when the calling plug corresponding to the same link connector as 85 said answering plug is inserted in a line jack to operate said second mentioned relay and thereby restore said first mentioned relay and said controlling means to their normal condition and render said receiver selectable again by a call initiating line.

101. A telephone exchange system including telephone lines extending from substations to an exchange switchboard, substation apparatus for initiating calls, a plurality of operators' positions at said switchboard; a group of link connectors, a telephone receiver and controlling means therefor, for each of said positions; an answering 105 plug and a calling plug for each of said link connectors, means at said exchange operative by said substation apparatus for automatically selecting one of said receivers and sounding therein the line designation of the 110 call initiating line, means whereby the insertion of one of said answering plugs at a position in a line jack of a calling line operates said controlling means of that position and thereby renders the receiver individual thereto non-selectable by a call initiating line; means, operative when the calling plug corresponding to the same link connector as 115 said answering plug is inserted in a line jack, to render said receiver selectable again by a call initiating line, and means to prevent the operation of said controlling means should said answering plug be inserted in a line jack of a line other than a line which is actually initiating a call.

102. A telephone exchange system including telephone lines extending from substations to an exchange switchboard, substation apparatus for initiating calls, a plurality of telephone receivers at said switchboard, a warning signal at said exchange, means at said exchange operative by said substation apparatus for automatically selecting one of said receivers and sounding therein the line designation of the call initiating line, means whereby a receiver can be selected by only one call initiating line at a time, means operative when there is no receiver selectable, whereby a line initiating a call operates said warning signal, and means operative as soon as there is a selectable receiver for discontinuing said signal.

103. A telephone exchange system including telephone lines extending from substations to an exchange switchboard, substation apparatus for initiating calls, a plurality of telephone receivers at said switchboard, a registering device, means at said exchange operative by said substation apparatus for automatically selecting one of said receivers and sounding therein the line designation of the call initiating line, means whereby a receiver can be selected by only one call initiating line at a time, and means operative when there is no receiver selectable, whereby a line initiating a call operates said registering device.

104. A telephone exchange system including telephone lines extending from substations to an exchange switchboard, substation apparatus for initiating calls, a plurality of operators' telephone receivers at said switchboard, a warning signal at said exchange, means at said exchange operative by said substation apparatus for automatically selecting one of said receivers, phonographic means for reproducing in said receiver words representing the line designation of the call initiating line, means whereby a receiver can be selected by only one call initiating line at a time, means operative when there is no receiver selectable, whereby a line initiating a call operates said warning signal, and means operative as soon as there is a selectable receiver for discontinuing said signal.

105. A telephone exchange system including telephone lines extending from substations to an exchange switchboard, substation apparatus for initiating calls, a plurality of operators' telephone receivers at said switchboard, a registering device, means at said exchange operative by said substation apparatus for automatically selecting one of said receivers, phonographic means for reproducing in said receiver words representing the line designation of the call initiating line, means whereby a receiver can be selected by only one call initiating

line at a time, and means operative when there is no receiver selectable, whereby a line initiating a call operates said registering device.

106. A telephone exchange system including telephone lines extending from substations to an exchange switchboard, link connectors for connecting said substations, substation apparatus for initiating calls, a plurality of telephone receivers at said switchboard, means at said exchange operative by said substation apparatus for automatically selecting one of said receivers and sounding therein the line designation of the call initiating line, means under the control of apparatus at said substations when connected by said link connectors for sounding an audible signal in the telephone receiver pertaining to the connecting operator and at the same time preventing said receiver from being selected by a call initiating line while said audible signal continues, and means to prevent the sounding of said signal and the selection of said receiver by a call initiating line when said connecting operator is engaged in completing a connection between substations.

107. A telephone exchange system including telephone lines extending from substations to an exchange switchboard, link connectors for connecting said substations, substation apparatus for initiating calls, a plurality of telephone receivers at said switchboard, means at said exchange operative by said substation apparatus for automatically selecting one of said receivers and sounding therein the line designation of the call initiating line, means under the control of apparatus at said substations when connected by said link connectors for sounding an audible disconnect signal in the telephone receiver pertaining to the connecting operator and at the same time preventing said receiver from being selected by a call initiating line while said audible signal continues, and means to prevent the sounding of said signal and the selection of said receiver by a call initiating line when said connecting operator is engaged in completing a connection between substations.

108. A telephone exchange system including telephone lines extending from substations to an exchange switchboard, link connectors for connecting said substations, substation apparatus for initiating calls, a plurality of telephone receivers at said switchboard, means at said exchange operative by said substation apparatus for automatically selecting one of said receivers and sounding therein the line designation of the call initiating line, means under the control of apparatus at said substations when connected by said link connectors for sounding an audible recall signal in the telephone receiver pertaining to the connecting opera-

tor and at the same time preventing said receiver from being selected by a call initiating line while said audible signal continues, and means to prevent the sounding of said signal and the selection of said receiver by a call initiating line when said connecting operator is engaged in completing a connection between substations.

109. A telephone exchange system including telephone lines extending from substations to an exchange switchboard, link connectors for connecting said substations, substation apparatus for initiating calls, a plurality of telephone receivers at said switchboard, means at said exchange operative by said substation apparatus for automatically selecting one of said receivers and sounding therein the line designation of the call initiating line, means under the control of apparatus at said substations when connected by said link connectors for sounding an audible disconnect and an audible recall signal in the telephone receiver pertaining to the connecting operator and at the same time preventing said receiver from being selected by a call initiating line while said audible signal continues, means to prevent the sounding of said signal and the selection of said receiver by a call initiating line when said connecting operator is engaged in completing a connection between substations, and means whereby the sounding of said recall signal prevents the sounding of said disconnect signal.

110. A telephone exchange system including telephone lines extending from substations to an exchange switchboard, link connectors for connecting said substations, substation apparatus for initiating calls, a plurality of telephone receivers at said switchboard, means at said exchange operative by said substation apparatus for automatically selecting one of said receivers, phonographic means for reproducing in said receiver words representing the line designation of the call initiating line, means under the control of apparatus at said substations when connected by said link connectors for sounding an audible signal in the telephone receiver pertaining to the connecting operator and at the same time preventing said receiver from being selected by a call initiating line while said audible signal continues, and means to prevent the sounding of said signal and the selection of said receiver by a call initiating line when said connecting operator is engaged in completing a connection between substations.

111. A telephone exchange system including telephone lines extending from substations to an exchange; phonographic means to indicate to an operator the line designation of a call initiating line, comprising a phonographic recording means of the characters used to designate said lines, said re-

cording means comprising a series of each of said characters repeated as many times as there are characters in each line designation; and means to cause said phonographic means to repeat said series of characters after a time interval has elapsed.

112. A telephone exchange system including telephone lines extending from substations to an exchange, substation apparatus for initiating calls, an operator's telephone receiver; voice recording means individual to the entire exchange for indicating to an operator the line designation of a call initiating line, comprising a recording means of the characters used to designate said lines, said recording means comprising a series of each of said characters repeated as many times as there are characters in each line designation; means to cause said voice recording means to repeat said series of characters after a time interval has elapsed, and selective means whereby any call initiating line automatically selects its proper line designating characters produced by said voice recording means and causes the corresponding line designation to be repeated in said telephone receiver.

113. A telephone exchange system including telephone lines extending from substations to an exchange switchboard, substation apparatus for initiating calls, a plurality of operators' call receivers at said switchboard, a warning signal, means at said exchange operative by said substation apparatus for automatically selecting one of said call receivers and indicating therein the line designation of the call initiating line, means whereby a call receiver can be selected by only one call initiating line at a time, and means operative whenever said exchange means for selecting call receivers does not operate correctly and select one of said call receivers, whereby a line initiating a call operates said warning signal.

114. A telephone exchange system including telephone lines extending from substations to an exchange switchboard, substation apparatus for initiating calls, a plurality of operators' call receivers at said switchboard, means at said exchange operative by said substation apparatus for automatically selecting one of said call receivers and indicating therein the individual line designation of the call initiating line, means whereby a call receiver can be selected by only one calling line at a time, becoming selectable again only after having been released from said calling line, means to select said call receivers in a regular sequence, thereby preventing a selected receiver from being again selected until after other call receivers inferior in order of precedence established by said sequence have been first selected and whereby all the calls initiated at said substations are distributed evenly amongst the

operators on duty at said switchboard, and automatic means, operative only should said means for selecting call receivers in a regular sequence be defective, to allow a previously selected call receiver to be again selected previous to said selection of other call receivers inferior in said order of precedence.

115. A call distributing telephone system comprising telephone lines extending from 10 substations to an exchange switchboard, a plurality of operators' positions at said switchboard, selective means for each of said lines; means comprising said selective means to give a plurality of said substations, when 15 initiating calls, access to any one of a plurality of said positions; means to prevent one of said positions from being given access to the selective means of but one call initiating line at a time; and means whereby 20 said selective means of lines not initiating calls are always normally connected to a non-selected position, being progressively so connected to other non-selected positions as soon as said normally connected position has 25 been given access to a call initiating line, thereby evading the progressive testing of said positions to find a non-selected one when a call is initiated at a substation.

116. A call distributing telephone system 30 comprising telephone lines extending from substations to an exchange switchboard, a plurality of sections at said switchboard, a plurality of operators' call receivers for each of said sections, line signaling apparatus individual to each of said sections and common to all of said receivers thereat, apparatus at said substations for initiating calls; means at said exchange, operative 35 when a line initiates a call, to select the line signaling apparatus of one of said sections and produce the line designation of the calling line in one only of said receivers at said sections, and means whereby each of said re-

ceivers has at one time or another exclusive control of the line signaling apparatus of its section, thereby allowing a plurality of lines to be connected to one of a plurality of call receivers by way of apparatus common to both a plurality of calling lines and call receivers.

117. A telephone exchange system including telephone lines extending from substations to an exchange switchboard, substation apparatus for initiating calls, a plurality of operators' call receivers at said switchboard; a lock-out release relay and a plurality of other relays at said exchange operative by said substation apparatus, a calling signal indicating means controlled by the operation of said plurality of relays, operating circuits 60 connecting said relays, a warning signal; means comprising said plurality of relays and circuits for selecting one of said receivers and means comprising said calling signal indicating means for indicating in said selected receiver the individual line designation of the call initiating line and means comprising said lock-out release relay and operative when there is no call receiver selectable, whereby a line initiating a call operates said warning signal.

118. A telephone exchange system including telephone lines extending from substations to an exchange, substation apparatus for initiating calls, line relays at said exchange less in number than said lines and normally connected thereto in groups and operative by said substation apparatus, means controlled by said relays for indicating to an operator at said exchange the line designation of a call initiating line, and means to prevent more than one call initiating line of a group from simultaneously indicating its line designation to said operator.

In testimony whereof I affix my signature. 85
HUBERT S. TURNER.
